UNITED STATES PATENT OFFICE.

WARREN W. CARPENTER, OF QUEENS VILLAGE, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed November 14, 1924. Serial No. 749,849.

This invention relates to telephone exchange systems, and more particularly to systems of the character in which automatic switching apparatus is employed in the establishment of conversational connections.

It is the principal object of this invention to better the service in an automatic telephone exchange by providing a new and improved trunking and controlling arrangement.

According to the foregoing object, there are provided a plurality of selective switches at a switching stage and a number of trunks outgoing from each such switch, each such trunk leading to a different one of a number of switches at a succeeding switching stage, together with means for selecting one of said trunks and for operating a switch at each stage to make connection with the selected trunk, whereby a connection may be extended through any switch at each stage in any desired direction.

A feature of the invention relates to a testing mechanism arranged to test all trunks leading from a given switch at the first stage and all switches at the second stage having access to the desired numerical direction and to select for use an idle one of said switches and an idle one of said trunks, the selection being such that the selected trunk leads to the particular switch selected.

Another feature relates to a system of the foregoing character in which the trunking arrangement is such that the apparatus imposes no limitation upon the size of the trunk groups.

Another object of the invention is to exercise control over a series of moving selective switches in a train in such a way that a plurality of said switches may undergo their setting operations simultaneously. This object is attained by the provision of a controlling marker which is separate from the switches and arranged to first determine the switches in the train to be used and then cause said switches to operate together to make connection with the proper points in their respective banks.

Another object is to increase the efficiency and availability of the controlling equipment in an automatic switching office. This object is realized in a system of the above described character where register senders and switch controlling markers are used by connecting the marker to the sender as soon as the office

code is received in order that the class information may be had, then releasing the marker to common use, and then reconnecting the sender to the same or another marker when the complete record has been received.

Another feature of the invention relates to an improved method of dividing the trunk groups leading to the final connecting switches, into first and second choice sub-groups.

Other features of this invention will become apparent from a consideration of the following detailed description and the appended claims.

Referring to the drawing, Figs. 1 to 22, inclusive, when arranged in the order shown in Fig. 25, illustrate a telephone exchange system embodying the features of this invention.

Fig. 1 shows one of a number of subscribers' lines, together with the line and group controlling mechanism in the central office.

Fig. 2 shows a line finder switch and a district selector switch.

Fig. 3 shows a trunk selector switch.

Fig. 4 shows a final selector switch having access to the called subscribers' line and P. B. X. trunks.

Fig. 5 shows a link finder for associating the links, each including a line finder and a district selector, with an idle register sender.

Figs. 6 to 12, inclusive, illustrate one of a number of register senders. Figs. 6 and 7 show the sender controlling equipment. Figs. 8 and 9 illustrate class relays and other controlling equipment. Fig. 10 shows the three office code registers. Fig. 11 shows the thousands, hundreds and tens registers. Fig. 12 shows the units and stations registers.

Figs. 13 and 14 illustrate a multi-contact relay sender connector for connecting the senders to the marker.

Figs. 15 to 20, inclusive, show one of the switch controlling markers. Fig. 15 illustrates the marker code registers and code translator. Fig. 16 shows the routing and controlling relays. Fig. 17 shows the numerical registers and numerical translator. Figs. 18 and 19 illustrate the controlling mechanism. Fig. 20 shows a portion of the testing relay equipment.

In the lower part of Fig. 21 is shown a district frame connector for associating the markers with the district frames. In the up-

per part of this figure is shown a trunk frame connector for connecting the different markers to the trunk selector switches.

In the right hand portion of Fig. 22 is shown one of a number of line test connectors. In the upper left portion of the figure is shown a connecting device for associating the markers with the line test connector. In the lower part of the figure is shown a portion of a connecting device for connecting the markers to the trunks of an outgoing trunk group.

Figs. 23 and 24 taken together comprise a schematic lay-out of a telephone exchange embodying the features of this invention.

General description of the system.

Considering the Figs. 23 and 24, a general description will first be given of the arrangement of the circuits and apparatus in a system of this character. The subscribers' lines 2300 enter the exchange and terminate in the banks of a number of line finder switches 2301, 2302, 2303, etc. Each of these finder banks is served by a number of selector switches, from each of which leads a trunk to a district selector switch.

The district selectors are distributed among a plurality of different frames 2304, 2305, 2306, 2307, 2308, etc. A portion of the trunks 2318 leading from the finder switches in the frame 2301 are shown distributed among the switches of the district frame 2304. Similarly, a portion of the trunks 2319 leading from the frame 2302 are distributed among the switches of the second district frame 2305. In like manner, the trunks leading from the various finder frames are distributed among the district frames in any desired fashion.

It is obvious that the number of district selector frames which may be provided for a telephone office is dependent upon different traffic factors. However, for the sake of explanation, it will be assumed that there are, in a system of this type, 33 different frames 2304, 2305, etc. Moreover, it is assumed that there are 33 trunk selector frames, of which 5 are shown, viz., the frames 2309 to 2313, inclusive. The multiple banks of the district frames and the trunk selector frames are connected together by means of trunks which are distributed among these different frames in a manner to be explained in detail hereinafter.

Each of the different trunk selector frames is served by a plurality of trunk selector switches each having access to all contacts in the bank. The trunks leading from these trunk selector switches are arranged in numerical groups, interoffice groups, and also serve for the various other purposes found in telephone practice.

For local service there are provided a number of final selector frames 2314, 2315,

2316, 2317, etc., which are divided into a suitable number of groups or choices in accordance with the directory numbering of the subscribers' lines. The switches at each of these final frames have terminating in them the trunks which lead from the trunk selector switches. On the basis of a ten-thousand line office, a convenient division of the final switching equipment is had by arranging all these frames into twenty-five different line choices. This means that each final line choice has four hundred different subscribers' lines to which connection may be made through such choice. Accordingly, there are twenty-five numerical groups of trunks leading from the trunk selector switches of the thirty-three different frames, each numerical group extending to a different one of the twenty-five choices.

For interoffice work, as many groups of interoffice trunks may be provided as there are distant offices with which connection is desired, and these trunks also lead from the trunk selector switches of the several frames.

Considering closely the method of distributing the trunks between the district and trunk connector frames, it will further be assumed that each of the district frames comprises a multiple panel bank having one hundred sets of multiple terminals therein. Likewise, it will also be assumed that each of the thirty-three trunk selector frames comprises a multiple panel bank having one hundred sets of terminals. The one hundred points on each of the district and trunk selector frames are further divided into three sections, each containing thirty-three sets of terminals. This division is illustrated in connection with the district frame 2304 in which two of the three thirty-three point sections, viz., 2320 and 2321, are shown. Similarly, this division is also illustrated in the frames 2305, 2309 and 2310. The purpose of this division is to provide a group of three trunks leading from each district frame to each separate trunk selector frame. That is to say, there are thirty-three separate groups of trunks each containing three trunks and each such group leading to a different one, and to only one, of the thirty-three different trunk selector frames. This means that a call appearing at any district selector frame has three equivalent paths over which it may be routed through any particular one of the trunk selector frames.

While there are thirty-three different frames both for the district and trunk selector switches, only five of each of these have been illustrated, and the method of wiring the trunks will be discussed on the basis of five, the same idea applying obviously to any number of the frames. Considering the frame 2304 as frame No. 1, 2308 as frame No. 2, 2307 as frame No. 3, 2306 as

frame No. 4, and 2305 as frame No. 5, and similarly for the trunk selector frames, it will be noted that the first trunk 2322 leads from the first point in the section 2320 to the first point in the corresponding section of No. 1 trunk frame 2309. The second trunk 2323 is connected to the second terminal in the second trunk frame 2313. The third trunk 2324 is connected to the third terminal in the No. 3 frame 2312. The fourth trunk 2325 is connected to the fourth terminal in the No. 4 frame 2311. The fifth trunk 2326 is connected to the fifth terminal of the No. 5 frame 2310. In a similar manner, the remaining trunks of the thirty-three trunk groups are connected to the corresponding trunks of the remaining trunk frames until finally the thirty-third trunk in the section 2320 of the No. 1 district frame 2304 is wired to the thirty-third trunk in the thirty-third trunk selector frame. With this arrangement, there is one trunk leading from the frame 2304 to each of the thirty-three trunk frames.

Commencing now with the thirty-fourth trunk of the frame 2304, viz, the first trunk 2327 in the second section 2321, this trunk, it will be seen, is connected to the corresponding first point in the second section of the first trunk frame 2309. The same procedure is repeated, each of the second group of thirty-three trunks leading to the corresponding points of the thirty-three trunk selector frames. Similarly, the third section of the first district switch 2304 is wired to the thirty-three trunk frames. Thus the first district frame 2304 has three trunks leading separately to the first trunk frame 2309, three trunks leading separately to the second frame 2313, and similarly three trunks to each of the remaining thirty-three trunk frames.

In a similar manner, the second district frame 2308 has its three sections of terminals connected to the terminals of the trunk frames, and the same is true for each of the remaining district frames. The result is, then, that any district frame has outgoing therefrom groups of trunks each leading separately to a different one of the thirty-three trunk frames.

The trunks of the several numerical and interoffice groups are distributed among the switches on all trunk selector frames, in order that a connection over any trunk group may be reached through any trunk frame. The number of trunks to be allotted to each of the trunk frames will, of course, depend upon the total number of trunks in the group. Assuming a group having sixty-six trunks therein, a suitable distribution may be had by allotting two of these trunks to each of the thirty-three different frames. If a group of forty trunks is desired, one way of

obtaining a group of this size is to allot one trunk to each of twenty-two different frames and two trunks to each of the remaining nine frames. If a group of thirty-three trunks is desired, one trunk is then allotted to each of the thirty-three different frames. Similarly, groups of any capacity may be had by the proper distribution of trunks among the trunk selector switches.

The controlling mechanism is illustrated diagrammatically in Fig. 24 and consists of a number of senders, such as 2400, and a number of markers, such as 2403. The links between the line finder and district selectors are associated with idle senders by means of link finders 2401. The senders are associated with the markers by means of sender connectors 2402 which are made up of multi-contact relays. The markers are associated with the district frames by means of the connector 2405 and with the incoming and final frames by means of the connectors 2406 and 2408.

Referring now to Figs. 1 to 22, the subscribers' lines, such as line 100, are shown terminating in the banks of the line finder switches 200. Each of the line finder switches 200 has terminating therein a trunk which leads to a district selector switch 205. Upon the initiation of a call, the line finder 200 operates to find the calling line and the link finder 500 operates to find the link including the line finder and district switches to which the calling line has been extended. The link finder 500 also selects an idle register sender. The calling subscriber thereupon manipulates his dial to transmit a number of a series of impulses representing the desired office. This office code is received by the counting relays shown in Fig. 6 and recorded on the code registers 1000, 1001 and 1002.

Immediately that the office record is received by the sender, the sender connector 1300 is operated to connect such sender to an idle marker and the office record is transmitted from the sender to the corresponding registers 1500, 1501 and 1502 in the marker. This record is then translated by means of the translator 1503 to register the different class requirements of the call. These class indications are then transmitted back to the sender and recorded on the class relays shown in Figs. 8 and 9.

If the call is one for a distant office, the marker proceeds to control the operation of the district and trunk switches to select an idle trunk leading to the proper office, and the sender thereafter transmits code impulses representing the numerical record. However, if the call is a local one, the marker after having transmitted the class information back to the sender, immediately releases and returns to common use.

The subscriber continues to dial the nu-

merical impulses and this record is set up on the registers 1100, 1101, 1102 and 1200, and the station's record, if any, is set up on the register 1201. As soon as the numerical record has been received, the sender connector 1300 is again operated to connect the sender either to the same or to some other idle marker. The numerical record is now transmitted from the sender to the marker, and the latter mechanism proceeds to control the district, trunk and the final switches to extend the calling subscriber's line through to the called subscriber's line in the local office.

13 The line finders 200, district selectors 205, trunk selectors 300, and final selectors 400, may be switches of the power driven type such as shown and described in the patent to Craft and Reynolds, No. 1,123,696, granted 20 January 5, 1915.

13 The line finders 200 may be of any suitable capacity having a number of sets of brushes operated by common brush tripping mechanisms such as illustrated in the patent to 23 McQuarrie, No. 1,177,044, granted March 28, 1916. In order to reduce the hunting time of any finder switch, the brush groups are divided into two subgroups, with certain switches having first preference in one subgroup and other switches having first preference in the second subgroup. This grouping is illustrated and described in the patent to 29 Irvine, No. 1,461,528, issued July 10, 1923. For the sake of simplicity in the present disclosure, the grouping arrangement has not been shown in full.

40 The district switching stage comprises, as hereinbefore explained, thirty-three separate switch frames or banks of contacts. Each of these frames has one hundred sets of stationary contacts multiplied to appear before any desired number of district selectors. Each district selector, such as the selector 205, consists of a brush rod and a single set 45 of brushes arranged to move over the bank and to make contact with each of the one hundred sets of terminals. The usual brush tripping feature is eliminated and the single set of brushes on each selector rod makes successive engagement with the terminals as it is driven over the bank.

50 Similarly, at the second switching stage, there are provided thirty-three trunk selector frames, each comprising a terminal bank 55 of one hundred sets of contacts. Each bank has arranged before it a desired number of trunk selector switches, each switch consisting of a single set of brushes mounted on a movable brush rod. Each of these sets of brushes has access to all of the one hundred sets of terminals appearing in each bank. The stationary terminals in the banks of the district frames are connected to the stationary terminals in the banks of the various 60 trunk selector frames by means of trunks 65

229, in the manner hereinbefore described in connection with the schematic diagram of Figs. 23 and 24.

Since each of the twenty-five final groups of lines is made up of four hundred different subscribers' lines, the final switches 400 are made up of panel banks having four hundred sets of contacts therein with brush rods each having four sets of brushes, each set of brushes serving one hundred different lines. 75 Each numerical group will have as many final selector switches 400 as is necessary to handle the probable number of simultaneous calls in that group. In this case it is necessary, to prevent wrong connections by maintaining the four sets of brushes on the final switch rod normally out of engagement with the contacts, only the desired set of brushes being tripped when the switch is taken into use.

80 In order to understand how the testing and selection of trunks is performed, a description will now be given of the testing equipment in the marker, shown particularly in Fig. 20. The set of testing relays 2000 is 85 designed to test the connecting trunks 229 which extend from the district frames to the trunk selector frames. In conjunction with this test, a test is also made to determine the busy or idle condition of all trunks 306 outgoing from the trunk selector frames in the desired direction; that is, either to the desired numerical group in the local exchange or to a desired interoffice group of trunks. Since there are ninety-nine connecting trunks 90 229 leading from any district frame to the various trunk selector frames, the testing relay set 2000 comprises a series of one hundred double wound testing relays 2010, 2011, 2012, etc.

95 It will be recalled that there are three connecting trunks 229 leading from any given district frame separately to each of the thirty-three trunk frames. That is to say, a call may be routed through any district frame to any one of the thirty-three trunk frames over either of three equivalent trunks 229. It is obvious that a numerical group of trunks or an interoffice group outgoing from the trunk selecting stage may 100 have as many trunks therein as desirable, and these trunks may be distributed among the different trunk selector frames in any suitable manner. For the sake of explanation, however, it will be assumed that the 105 largest group of trunks outgoing from the trunk selector frame comprises sixty-six trunks. A suitable distribution of a group of trunks of this size may be had by allotting two trunks to two different trunk selectors 110 300 on each of the thirty-three different trunk selector frames. Therefore, it appears that with a group of sixty-six trunks outgoing from a numerical stage distributed in 115 the manner explained, a call may be routed 120 125 130

through a given district frame and through a given trunk selector frame over either one of three connecting trunks 229 and either one of two numerical trunks 306. The purpose of the testing equipment is to ascertain which trunk selector frame has a connecting trunk 229 incoming thereto from the particular district frame to which a connection has been extended and which connecting 10 trunk is idle simultaneously with the idle condition of a numerical trunk 306 outgoing therefrom in the proper direction.

On the assumption of a maximum of two numerical trunks 306 outgoing from any 15 trunk selector frame in any given direction, it is necessary to provide in the testing equipment a further group of testing relays for each trunk selector frame. Two of these groups 2020 and 2021 are illustrated. The 20 group of relays 2020 cooperate with the particular three tests relays 2000 which relate to the group of three connecting trunks incoming from any desired district frame to the particular trunk frame to which said 25 group 2020 is individual. Similarly, the second group 2021 cooperates with three other test relays 2000 relating to the three trunks incoming from any district frame to the particular trunk frame to which said 30 group 2021 is individual. Likewise, there would be provided thirty-one other of these groups of relays, each relating to a different trunk frame. The relay 2022 in the group 35 2020 is for testing the first trunk 306 outgoing from the particular trunk frame in any numerical direction. The second relay 2028 is for the purpose of testing the second trunk outgoing from such frame in any numerical direction. Likewise, the relays 2025 40 and 2030 are for testing the first and second trunks outgoing from another trunk selector frame in any numerical direction.

The double wound test relays 2000 are numbered consecutively from 1 to 100 and 45 serve to test the one hundred trunks outgoing from any district frame in consecutive order. However, since the trunks are distributed, as explained in connection with the diagram of Figs. 23 and 24, between the district and trunk selecting stages, the three 50 test relays 2000 which constitute a group relating to the group of trunks incoming to a given trunk selector frame, are spaced from each other thirty-three relays apart, inasmuch as the trunks outgoing from the district frame are similarly spaced. For example, the three test relays relating, respectively, to the three trunks incoming to the trunk frame represented in Fig. 3, are the 55 first, thirty-fourth, and sixty-seventh relays in the chain, viz the relays 2010, 2012 and 2015. If, for example, the trunk 229 is the first trunk in the district frame represented in Fig. 2 outgoing and appearing as the first 60 trunk in the trunk selector frame represent-

ed in Fig. 3, then the relay 2010 is for the purpose of testing this particular trunk. The second trunk leading from this district frame to this particular trunk frame is the thirty-fourth trunk in the bank, and consequently the thirty-fourth relay 2012 is for the purpose of testing this trunk. Similarly, the third trunk is the sixty-seventh trunk in the bank, and therefore the sixty-seventh relay 2015 is for the purpose of testing this 70 trunk. The group of test relays 2020 relating to the two outgoing trunks in any numerical group are associated with these three test relays 2010, 2012 and 2015.

A second group of relays including the 80 second relay 2011, the thirty-fifth relay 2013, and the sixty-eighth relay 2016, serve to test the three connecting trunks outgoing from the district frame shown in Fig. 2 to another trunk selector frame. The group of test 85 relays 2021 cooperate with this set of relays 2011, 2013 and 2016. In a similar manner, the remaining test relays are divided into sets of three, each relating to a group of three trunks outgoing from the said district 90 frame to the various other trunk frames. Also, in a similar manner, the testing relays 2000 may be associated with any of the other thirty-three district frames and serve to test the thirty-three groups of three trunks each 95 outgoing to the thirty-three different trunk frames.

Considering again a numerical group of trunks 306, including sixty-six trunks therein, it will appear that if a call has been 100 routed to a given district frame and it is desired to further extend the calling line into this particular numerical group of sixty-six trunks, the extension may take place through any one of the thirty-three trunk selector 105 frames each of which has three incoming available paths and two outgoing available paths. The particular frame to be used will depend upon the determination of the testing relays. That is to say, the first trunk 110 selector frame will be used for extending the call which has incoming thereto from the given district frame an idle one of the three connecting trunks and also outgoing therefrom an idle one of the two 115 numerical trunks leading in the proper direction. If it happens that all three connecting trunks leading from the district frame are busy, then all three relays 2010, 2012 and 2015, for instance, are operated, 120 and the testing mechanism tries out the next trunk selector. If, on the other hand, one or more of the connecting trunks are idle, but both trunks outgoing in the required direction are busy, then both relays 2022 and 2028, for instance, are operated and again 125 the testing mechanism tries out the next trunk selector frame.

Should it be desired to have only thirty- 130 three trunks in a given group, then only half

of the relays 2022, 2028, etc., are wired through the connecting device 2200 to the sleeve conductors of the trunks. For instance, the trunks corresponding to relays 2028 and 2030 in the groups 2020, 2021, etc., are omitted and provision is made for cancelling the effect of these relays at all frames. For this purpose, a cancelling relay 1923 is provided. This relay is operated whenever a call is being made to the group of thirty-three trunks and takes the place of the relays 2028, 2030, etc.

A group of forty trunks may be tested by providing a cancellation relay for cancelling one trunk on twenty-six trunk selector frames and leaving two trunks on each of the remaining fourteen frames. The relay 1924 may serve for this purpose. It would be wired as illustrated in connection with relay 1923 in such a fashion as to substitute for the relays 2028, 2030, etc., the first twenty-two trunk selector frames, and the wiring from these relays to the connecting device 2200 would be omitted. The relays 2028 and 2030 of the remaining nine groups relating to the remaining nine trunk selector frames, would not be cancelled by the relay 1924, but would have their windings wired through the connecting device 2200 for the purpose of testing the sleeve conductors of corresponding trunks. Similarly, other cancellation relays may be provided for obtaining a test of trunk groups of any desired size.

There are provided twenty-five connecting devices similar to the device 2200, one for each of the final line choices. Each one of these devices serves to connect any one of the several markers to the apparatus associated with its particular choice, or final connecting group. The device 2200, for instance, serves to connect the test leads from the various markers to the sleeve conductors of all trunks leading from the trunk selector switches 300 to the particular numerical choice in which the line 401 occurs and to which the final selector 400 has access. Device 2200 also connects the various selector test leads in the marker to the line test connector comprising the structures 2203 and 2201. The purpose of this line test connector is to select the proper one of the four hundred lines in order that the same may be tested and a proper condition placed thereon for identifying it to the final switch 400.

There are also provided a number of connecting devices 2208, one for each of the several groups of trunks outgoing from the trunk selecting stage to distant offices. The function of these devices is similar to that of the connecting devices 2200.

Each register sender includes three controlling sequence switches 520, 620 and 710. The contacts controlled by the switch 520 all appear in Fig. 5, the contacts of sequence

switch 710 appear in Fig. 7 and within the broken rectangles in Fig. 6, and the remaining contacts in Fig. 6 are controlled by the timing sequence switch 620. These switches may be of the type shown and described in the patent to Reynolds and Baldwin, No. 1,127,808, issued February 9, 1915.

From the foregoing general description, it will be seen that a very desirable method of routing calls through the switching stages is accomplished by the manner in which the district selector frames are interconnected with the trunk selector frames, together with the means for testing the incoming and outgoing trunks to ascertain an available path. One of the great advantages that can be secured from a trunking plan of this character is the ease with which selector switches may be appropriated to different trunk groups without disturbing other elements of the system. Since the trunks outgoing from the trunk selecting stage have no fixed positional or space relation to each other from a numerical grouping standpoint, they may be reassigned at will, some groups being enlarged and other groups being decreased without it being necessary to disturb the trunks not otherwise affected by the reassignment.

Another advantage of this system is the uniformity with which the load of the exchange is distributed over the entire switching apparatus. Any call arriving at the district stage may be routed through the trunk selecting stage over any one of the entire number of switch frames at such latter stage. Other advantages are to be found in the simplified form of switching mechanism required, the speed and efficiency of their operation, and the reliability characterizing the manner in which the switches are governed by the controlling markers.

Detailed description of a local connection.

It will now be assumed that the subscriber of line 100 desires to converse with the subscriber of line 401 terminating in the same exchange.

Operation of line finder and link finder.—The calling subscriber on initiating a call, causes the operation of line relay 101. Relay 101 closes an obvious circuit for operating the group relay 103. Relay 103 closes an obvious circuit for relay 108 and also operates the trip relay 105. The circuit for relay 105 may be traced from ground, through the contact of relay 123, contact of relay 103, back contact of slow-release relay 104, left winding of relay 105, contact of relay 124, outer left contact of relay 110, to battery. Relay 105 locks in a circuit from ground, through its right winding and contact, left back contact of relay 106, to battery through the winding of relay 110. Relay 110 also operates in this circuit. The relay 105 operates the trip magnet 203,

which prepares the trip rod for tripping the brushes 230 when the brush rod is started in operation. The circuit of magnet 203 is obvious from inspection. Relays 105 and 110 5 also complete a circuit for relay 104 which may be traced from battery, through the winding of said relay, front contacts of relays 105 and 110, to ground. Relay 104 locks in a circuit from battery, through its winding and contact, contact of relay 103, to ground at the contact of relay 123.

Relay 110 at its outer left contact, opens the operating circuit of relay 105. Relay 110 closes a circuit for relay 207 to start the 15 allotted line finder 200 in motion. The circuit for relay 207 may be traced from battery, through its winding, back contact of "make busy" relay 208, conductor 231, through the brush 125, (assuming the allotter 120 to be standing in position for allotting this finder), right contact of relay 109, the normal contact of relay 111, to ground at the outer right contact of relay 110. Relay 207 locks through its inner left 23 contact to ground through back contacts of relays 204 and 206. Relay 207 causes the operation of relay 111 in a circuit from battery, through the winding and right normal contact of relay 111, conductor 126, middle left contact of relay 208, to ground at the middle left contact of relay 207. Relay 111 locks to ground at the right contact 39 of relay 110. Relay 111 at its inner left contact closes a circuit for the stepping magnet 121 of the allotter switch 120 for advancing this switch to allot the next line 45 finder.

Relay 207 in operating, closes an operating 50 circuit for the up-drive power magnet 201. This circuit may be traced from battery, through the magnet 201, outer left contact of relay 207, conductor 232, commutator segment 233, to ground through the associated brush. Magnet 201 causes the brush 55 shaft to move upwardly. In the first part of the movement, the set of brushes 230 is tripped to the exclusion of all other sets of brushes and makes contact with the terminals of the calling lines in its section. 60 During the early part of the movement of the brushes 230, the commutator brush 234 makes momentary engagement with the segment 235, resulting in the shunting of relay 105. This shunt circuit may be traced from 65 battery, through the winding of relay 110, the left back contact of relay 106, thence through the inner left back contact of relay 107, outer right contact of relay 111, conductor 127, outer left contact of relay 206, segment 235, brush 234, to ground. Relay 105 releases, in turn opening the holding 70 circuit of relay 110. Relay 110 also releases and causes the release of relay 111.

Also, as soon as the brushes have started

in movement, the commutator brush 236 engages the segment 237, completing a circuit over conductor 238, through the right winding of relay 208, to battery. Relay 208 operates to indicate that the line finder is busy. While the line finder is in operation, 75 relay 211 is energized to temporarily open the talking conductors. The circuit for this purpose may be traced from battery, through the lower winding of said relay, inner right front contact of relay 207, conductor 238, 75 to ground through the commutator 237.

When the brushes 230 of the finder reach the terminals of the calling line, the test relay 204 is operated in a circuit from ground, through the inner right contact of 80 relay 206, winding of relay 204, inner left contact of relay 221, through the lower brush 230 and its associated terminal, thence over conductor 240, right front contact of relay 101, left hand winding of relay 123, to battery. Relay 123 operates and releases the 85 relay 104.

It will be noted that relay 129 operates through its left winding at the time relay 104 is energized. Relay 129 closes a circuit 90 through the right winding of relay 123. This winding, however, is insufficient to operate the relay 123, but will hold the relay in its operated condition after it has been energized by means of its left hand winding, 95 as above described.

The test relay 204 in operating, opens the holding circuit of relay 207. Relay 207, however, remains temporarily operated to hold the circuit of the power magnet 201 100 closed until the brushes 230 have accurately centered on the terminals of the calling line. The temporary holding circuit of relay 207 may be traced from battery, through its winding and contact, conductor 241, to the 105 centering commutator 242. When the brushes are accurately centered, relay 207 releases and opens the circuit of the up-drive power magnet 201, causing the switch to come to rest. 110

Relay 207 on releasing, causes the release of relay 211, which in turn closes a circuit for operating the relay 218. This circuit may be traced from battery, through the winding of the latter relay, back contact of 115 relay 211, outer right contact of relay 206, inner right back contact of relay 207, to the grounded conductor 238. With relay 218 operated, a circuit is completed as follows for the cut-off relay 102 of the calling line: 120 battery, through the winding of said relay, conductor 130, through the next to the lowest brush 230, conductor 243, outer right contact of relay 207, left normal contact of relay 219, inner left front contact of relay 218, back 125 contact of relay 211, outer right contact of relay 206, inner right contact of relay 207, to the grounded conductor 238. Relay 102

releases the line relay 101, which in turn releases the group relay 103.

At the time relay 207 is first operated, the relay 209 is energized to initiate the operation of the link finder 500. The circuit of relay 209 leads from battery, through its left winding, outer right contact of relay 208, outer left contact of relay 207, conductor 232, to ground through the commutator 233. Relay 209 immediately locks through its right winding and contact, to ground at the inner upper contact of relay 212. Relay 209 closes the start circuit for operating the relay 503. This circuit may be traced from battery, through the winding of relay 503, conductor 522, contact of relay 209, to ground at the contact of relay 212.

Relay 503 completes a circuit for the up-drive power magnet 510 of the link finder 501. This circuit may be traced from battery, through the winding of said magnet, back contact of relay 509, front contact of relay 503, outer left contact of relay 505, left back contact of relay 504, back contact of relay 507, to ground at the back contact of relay 508. The brushes of the switch 501 are driven up over the terminals in the bank until they encounter the terminals representing the link shown in Fig. 2. When these terminals are reached, a circuit is completed from battery, through the inner left contact of relay 209, conductor 244, through the terminal and brush of the switch 501, outer left contact of relay 509, normal contacts of relay 505, conductor 523, back contact of relay 508, left hand low resistance winding of relay 506, right hand high resistance winding of said relay, through the winding of the marginal relay 507, to ground. Relay 506 operates in this circuit, but relay 507 being marginal does not operate at this time. Relay 506 shunts its right hand high resistance winding, but relay 507 still remains deenergized by means of a shunt which leads to ground through the centering commutator 524. When the brushes of the switch 501 are accurately centered, the shunt is removed and relay 507 operates in series with the low resistance winding of relay 506. Relay 507 opens the circuit of the power magnet 510 and the brushes of the switch come to rest.

Relay 507 in operating, closes an energizing circuit for relay 505 traceable from battery, through the winding and normal contact of relay 505, front contact of relay 507, to ground at the back contact of relay 508. Relay 505, after an interval, closes its contacts and completes an operating circuit for relay 504. Relay 505 in operating locks in a circuit from battery, through its winding and front contact, conductor 525, normal contacts of relay 512, brush and terminal of switch 501, conductor 526, lower winding of relay 212, to ground. Relay 212 operates in

this circuit and releases the relay 209, which in turn causes the release of relay 503. The operation of relay 505 causes the release of the test relays 506 and 507.

The sender selector 502 is next operated to select an idle register sender for association with the link shown in Fig. 2. The switch 502 is arranged to be driven in a hunting movement both up and down over its banks of terminals. For this purpose, there is provided a mechanically locking device consisting of relays 513 and 516. When the switch reaches its uppermost set of contacts, the commutator brush engages the segments 527, energizing the relay 513. The relay 513 unlocks the armature of relay 516, permitting the same to release and close the circuit of the down-drive power magnet 250. The brushes are then driven downwardly until they reach the lowermost contacts in the bank. At this time, the commutator brush engages the lowermost segment 528, closing a circuit for relay 516 which attracts its armature to the position where it is mechanically locked, also closing the circuit for the up-drive power magnet 514, and the brushes are thereupon driven upwardly again over the bank.

Assume that the mechanism is in the condition shown in the drawing at the time it is desired to select an idle register sender. Hence when relay 507 releases the down-drive power magnet 515 is operated in a circuit from battery through the winding of said magnet, back contact of relay 516, front contact of relay 504, back contact of relay 507 to ground at the contact 508. The magnet 515 causes the brushes to move downwardly until they encounter the terminals of an idle register sender.

When the idle sender is reached, a circuit is closed from battery through the contact of relay 623, inner right contact of relay 604, conductor 624, terminal and brush of the switch 502, conductor 529, front contacts of relay 505, conductor 523 and thence through the windings of relays 506 and 507 to ground. These relays operate in conjunction with the centering commutator 530 as explained in connection with the switch 501 and cause the switch 502 to come to rest. Relay 507 in operating closes a circuit from battery through the left winding of relay 512, front contact of relay 504, front contact of relay 507 to ground. Relay 512 operates and completes a circuit traceable from battery through the winding of the holding relay 604 in the sender, back contact of relay 603, the terminal and brush of switch 502, right winding and front contact of relay 512 and thence to ground through the lower winding of relay 212 as hereinbefore traced. Relay 512 places ground potential on the test brushes of both switches 501 and 502 to prevent another link finder similar to the finder

500 from selecting either the link shown in Fig. 2 or the seized sender. Relay 512 also operates the cut-in relay 508. Relay 508 releases the test relays 506 and 507. Relay 512, 5 when operating, also releases the relay 505 which, in turn, releases the relay 504. The apparatus is now in a stable condition and the calling subscriber's line has been extended through to the selected one of the register senders. 10

Setting the register sender.—The subscriber's line is included in series with the impulse relay 600 by means of a circuit which may be traced from battery through 15 the right winding of said relay, normal contact of relay 625, conductor 626, thence through the link finder 500 to conductor 531, lowermost front contact of relay 212, lowermost back contact of relay 211, thence over 20 the ring-side of the subscriber's line 100 and returning over the tip side of the line through the upper back contact of relay 211, uppermost front contact of relay 212, conductor 532, through the link finder 500 to 25 conductor 627, thence through the outer right contact of relay 625 and resistance 628 to ground. The impulse relay 600 operates in this circuit and closes an obvious circuit for the slow-release relay 601. Relay 601 completes 30 a circuit for relay 602 which in turn locks over conductor 629 to ground at the left front contact of the holding relay 604. Relay 600 also closes a circuit for the first counting relay 613. This circuit may be 35 traced from ground through the front contact of relay 600, conductor 630, left back contact of relay 605, outer right contact of relay 610 thence through the right back contacts of relays 609, 608 and 607 through 40 the winding of relay 613 to battery. Relay 613 operates and prepares a circuit from battery through its winding and the winding of relay 607, right contact of relay 613, left back contact of relay 608 to conductor 631. 45

The apparatus is now in a stable condition ready for the receipt of impulses from the subscriber's dial. A source of dial tone current may be applied to the calling subscriber's line in any well-known manner to inform him that the central office equipment is ready for the receipt of impulses. For the sake of illustration, it will be assumed that the office designation is represented by 50 three series of impulses, the first comprising four impulses, the second four impulses and the third three impulses. These three impulse series may, of course, stand for three letters of the alphabet which, in turn, may be the abbreviation of an office name. It will also be assumed that the numerical portion of the designation representing the called subscriber's line is 1 2 3 4. Accordingly, the calling subscriber first manipulates his dial to send a series of four im- 55 pulses. Upon the first opening of the line, relay 600 releases opening the circuit of relay 601 which, being slow to release, however, remains energized during the interval between impulses. Relay 600 in releasing 70 completes a circuit from ground through its back contact, left contact of relay 601, conductor 632, winding of slow-release relay 633 to battery. Relay 633 operates the relay 606 in a circuit which may be traced through 75 the normal contacts of relay 605 thence through the right front contact of relay 633, conductor 635, conductor 636 to ground at the contact of relay 604. Relay 606 locks in a circuit through its winding, contact of relay 605, left-hand front contact of relay 606 to the grounded conductor 635. 80

Relay 607 operates in series with relay 613, the shunt having been removed at the front contact of relay 600. 85

When the line closes at the end of the first impulse, relay 600 again energizes and in response to the second, third and fourth impulses counting relays 614, 608, 615, 609, 616 and 610 operate and relays 614, 608, 615 and 90 609 release. When relay 615 operates it operates relay 634 and the latter relay locks. After the last impulse relay 600 remains energized for a prolonged interval. When relay 633 first operates it closes a circuit for 95 operating relay 622 which may be traced from battery through the winding of the latter relay, left back contact of relay 621, conductor 637, left contact of relay 633, conductor 638 to ground at the right contact of relay 621. Relay 622 operates and closes a circuit from battery through its winding and left contact and through the left-hand winding of relay 621 to ground. Relay 622 locks in this circuit, but due to the resistance 100 of relay 622 and due to the direct shunt around the left winding of relay 621, the latter relay does not operate. Relay 622 closes an operating circuit for relay 517. 105 This circuit may be traced from battery through the winding of relay 517 to ground at the contact of relay 622. The purpose of the relay 517 is to connect the impulse leads from the counting relays through contacts of the sequence switch 520 to the first register 1000. 110

At the end of the interval following the first impulse series transmitted by the subscriber, the slow-release relay 633 becomes 115 released and a circuit is completed for the register relay 1003. This circuit may be traced from battery through the winding of said relay, conductor 1004, contacts of sequence switch spring 533, the outer right back contact of relay 517, conductor 534, through the inner left contact of relay 610, inner right contact of relay 606, right back contact of relay 633 to the grounded conductor 635. Relay 1003 locks in a circuit 120 from battery through its winding and inner 125 contacts of sequence switch 520. The circuit 130 from battery through its winding and inner contacts of sequence switch 520 is completed through the outer right back contact of relay 517, conductor 534, through the inner left contact of relay 610, inner right contact of relay 606, right back contact of relay 633 to the grounded conductor 635. Relay 1003 locks in a circuit from battery through its winding and inner contacts of sequence switch 520.

left contact, conductor 1005, outer left front contact of relay 634, to the grounded conductor 635.

With the relay 1003 energized a circuit is closed for driving the sequence switch 520 out of position 1 and into position 2. This circuit may be traced from battery through the winding of the sequence switch magnet 520, upper left contact 535 through the inner right contact of relay 1003, conductor 1006 to the grounded conductor 636. When the sequence switch reaches position 2, a circuit is closed for relay 605 traceable from battery through the winding of said relay, conductor 639, outer left front contact of relay 622, lower left contact 537 of sequence switch 520, conductor 640, through the middle right contact of relay 1003, conductor 1008, conductor 641, inner right contact of relay 606 through the right back contact of relay 633 to the grounded conductor 635. Relay 605 locks momentarily in a circuit closed through its winding and make-before-break contact. Relay 605 in operating, opens the holding circuit of relay 606, which releases and in turn opens the operating and locking circuits of relay 605, whereby the latter relay becomes deenergized. During the operating period of relay 605, the energized counting relays are released.

When relay 633 operates, it opens the original operating circuit of relay 622. However, the opening of this circuit removes the shunt around the left winding of relay 621, permitting this latter relay to operate in series with relay 622.

Upon the release of the relay 605 following the first series of impulses, the above traced circuit is closed from ground, through the front contact of the impulse relay 600 for operating the first counting relay 613 as hereinbefore traced. The apparatus is now ready to receive the second series of impulses. In response to the second series of impulses, the counting relays are operated as above explained until the relays 616 and 610 have been energized and locked and all preceding counting relays have been released. Moreover, relays 633 and 606 are operated as above described. When relay 633 operates, a circuit is completed from battery, through the right winding and front contact of relay 621, conductor 638, left contact of relay 633, conductor 637, left front contact and left winding of relay 621, to ground. This circuit shunts the relay 622, which thereupon releases and causes the release of relay 517.

After an interval has expired following the second series of impulses, relay 633 releases and closes a circuit for operating the register relay 1010. This circuit may be traced from battery, through the winding of relay 1010, conductor 1011, upper left contact of sequence switch spring 538, outer

right back contact of relay 517, conductor 534, thence through the inner left contact of relay 610, to ground as above traced. Relay 1010 locks through its inner left contact to ground over conductor 1005. With relay 1010 operated, the control sequence switch 520 is advanced into position 3 by means of a circuit traceable as follows: battery, through the winding of the sequence switch magnet, upper right contact 535, conductor 539, inner right contact of relay 1010, conductor 1006, to ground. When sequence switch 520 reaches position 3, a circuit is closed as follows for the operation of relay 605: battery, through the winding of said relay, conductor 639, left back contact of relay 622, upper contacts of sequence switch spring 540, conductor 642, contact of relay 1010, to ground over conductor 1008 as previously traced. Relay 605 causes the release of the counting relays and also of relay 606, and the latter relay causes the release of relay 605.

At the time relay 633 releases, it opens the holding circuit of relay 621, permitting this latter relay to release.

The subscriber next transmits a series of three impulses representing the third character in the office designation. In response to these impulses, counting relays 609 and 615 are operated. Relay 633 also operates and causes the operation of relays 606 and 622. After an interval following the third series, relay 633 releases, causing the operation of relay 621. Relay 633 also closes a circuit for operating the register relay 1012. The circuit for this relay may be traced from battery, through the winding thereof, conductor 1013, upper left contact 541, inner left front contact of relay 517 (this latter relay being energized due to the operation of relay 622), conductor 542, inner left contact of relay 609, to ground over conductor 641 as previously traced. Relay 1016 is also operated in a circuit from battery, through its winding, conductor 1017, upper left contact of spring 547, outer left front contact of relay 517, conductor 548, inner left front contact of relay 616, inner left contact of relay 609, to ground over conductor 641. It will be recalled that relay 616 operates as soon as the impulse relay 600 closes following the transmission of the last impulse. Relays 1012 and 1016 lock through their windings and inner left contacts, conductor 1014, conductor 643, to ground through the lower right contact of sequence switch spring 543.

With relay 1012 operated, the sequence switch 520 is advanced into position 4 by means of a circuit from battery, through the winding of the sequence switch magnet, lower right contact of spring 535, conductor 544, inner right contact of relay 1012, to ground over conductor 1006. With the se-

quence switch 520 in position 4, relay 605 is operated by means of a circuit from battery, through the winding of said relay, conductor 639, left front contact of relay 622, upper left contact of spring 537, conductor 644, through the middle right contact of relay 1012, to ground over conductor 1008. Relay 605 puts the impulse circuit in condition to receive the next set of impulses in a manner hereinbefore explained.

The subscriber now transmits a single impulse representing the first digit in the numerical part of the designation, causing the operation of relays 633 and 607. Relay 633 operates and causes the operation of relay 606 and the release of relay 622. Relay 622 releases the relay 517. After an interval has expired, relay 633 releases, causing the release of relay 621. Relay 633 also completes a circuit for the operation of relays 1105 and 1106 of the thousands register 1100. The circuit for these relays may be traced from battery, through their windings in parallel, thence over conductor 1015, upper right contact of sequence switch spring 545, inner left back contact of relay 517, conductor 542, thence through the inner left contact of relay 607, to ground over conductor 641 as above traced. Relays 1105 and 1106 lock through the inner left contact of relay 1105 to ground over conductor 1014. The operation of relay 1105 causes the advance of sequence switch 520 out of position 4 and into position 5, and in this position a circuit is closed as follows for operating relay 605: battery, through the winding of the latter relay, conductor 639, left back contact of relay 622, right contacts of spring 546, conductor 645, middle right contact of relay 1105, to ground over conductor 1008. Relay 605 will close the impulse circuit ready for the receipt of the next series of impulses.

In a manner similar to that already explained, the next three series of impulses are transmitted to the exchange and recorded on registers 1101, 1102 and 1200. From inspection, it will be found that for the number assumed, the relays 1106, 1107, 1108 and 1202 are operated. After the units register 1200 has been set, sequence switch 520 is driven out of position 7 and into position 8.

For a more complete description of the manner in which the impulse receiving mechanism consisting of the counting and controlling relays functions, together with the recording relays, reference is made to the copending application of W. W. Carpenter, Serial No. 703,362, filed April 1, 1924, issued as Patent No. 1,600,399 September 21, 1926.

Association of the register sender with an idle marker.—As soon as the office record has been received and recorded on the registers 1000, 1001 and 1002, the sender is immediately connected to an idle marker

through the sender-connector 1300 and the office record is transferred to the marker for the purpose of determining the nature of the call. If, as in the present case, the call is a local one, the marker having analyzed the office record transfers certain information back to the sender and thereupon the marker becomes released and restores for common use. All this takes place while the numerical portion of the designation is being received in the sender.

At the completion of the office designation, it will be recalled that the control sequence switch 520 advances into position 4. In this position the relay 805 is operated by means of a circuit from battery, through the winding of said relay, inner right back contact of relay 804, outer right contact of relay 808, conductor 809, upper left contact of sequence switch spring 550, to ground. Relay 805 locks through its inner right contact, outer right back contact of relay 804, conductor 810, normal contact of relay 808, to ground over conductors 811 and 629. Relay 1406 individual to the sender is now operated at the sender connector 1300. The circuit for relay 1406 may be traced from ground through the right back contacts of relays 1405 and 1404, left winding of relay 1406, conductor 1408, to battery through the inner left contact of relay 805. Relay 1406 locks in a circuit traceable over conductor 1408, right winding and front contact of said relay, thence through the back contacts of the succeeding similar relays through the winding of relay 1405 to ground. Relay 1405 also operates and closes a circuit through the outer left contact of relay 1406 to operate the multi-contact relay 1301 individual to the sender shown.

Relay 1406 also causes the operation of relay 1401 which relates to the particular marker illustrated in the drawing to which the sender shown has first choice access. The circuit for relay 1401 may be traced from battery, through the inner left contact of relay 1406, contact of relay 1403, right contact of busy relay 1400 (assuming the marker shown is idle at this time), conductor 1409, front contact of relay 1301, back contact of relay 1302, conductor 1308, left back contact of relay 1400, left winding of relay 1401, to ground at the back contact of relay 1402. Relay 1401 locks in a circuit traceable through its right winding and front contact to ground through the winding of relay 1402. Relay 1402 operates and closes an obvious circuit for the make-busy relay 1400. Relay 1402 also completes a circuit for relay 1403 traceable from battery, through the winding of the latter relay, inner left contact of relay 1401, to ground at the front contact of relay 1402. Relay 1403 opens the circuit leading to every relay similar to the relay 1401. Relay 1403

1402 furthermore operates the multi-contact relay 1306 which is individual to the selected idle marker. The circuit for this purpose is traceable from battery, through the winding of relay 1306, outer left contact of relay 1401 to ground at the front contact of relay 1402. Relay 1306 operates the relay 1404 in a circuit from battery, through the right winding of the latter relay thence 19 through the contact of relay 1306, to ground at the right front contact of relay 1405. Relay 1404 opens up the circuit to prevent the operation of every relay similar to relay 1406. With relays 1301 and 1306 operated, 15 the conductors leading from the sender are extended through to the selected idle marker. Immediately that the marker is connected to the sender, the holding ground supply relay 1611 is operated by means of 20 a circuit which may be followed from battery, over conductor 1408, as hereinbefore traced, thence through the connector 1300, conductor 1309, conductor 1616, outer left contact of relay 1907, conductor 1926, winding of relay 1611, to ground. Relay 1611 locks through its inner right contact.

Transfer of the office record from the sender to the marker and establishment of class record in sender.—The office record established on the registers 1000, 1001 and 1002 is now transferred to the corresponding registers 1500, 1501 and 1502 of the marker. Accordingly, a circuit is closed for operating the relay 1508 which corresponds to the 30 relay 1003 of register 1000. This circuit may be traced from battery, through the winding of relay 1508, thence through the connector 1300, conductor 1110, outer right contact of relay 1003, to ground. Also, relay 1509 of register 1501 is operated in a 35 circuit from battery, through the winding of said relay, through the connector 1300, conductor 1111, to ground at the outer right contact of relay 1010. In a similar manner, 40 relays 1510 and 1511 corresponding to relays 1012 and 1016 are operated in the register 1502. Moreover, the remainder of the relays 45 of the registers 1500, 1501 and 1502 are operated over circuits traceable from battery, through their various windings in parallel, thence through connector 1300, thence over 50 the respective conductors 1112, through the outer right back contacts of the respective deenergized relays of the registers 1000, 1001 and 1002, and thence over conductor 55 1018, left back contact of relay 803, conductor 813, through the connector 1300, conductor 1310, back contact of relay 1505, conductor 1512, middle right back contact 60 of relay 1608, to ground at the contact of relay 1611. When all of the register relays 65 of the marker have operated, a circuit is closed for relay 1504 which leads through a series of contacts on all of said relays, to

ground. Relay 1504 locks through its right contact to the grounded conductor 1512 and operates the relay 1505, which in turn operates the relay 1506. Relay 1505 opens the above traced circuits for the relays of registers 1500, 1501 and 1502, and all of these 70 relays release except relays 1508, 1509, 1510 and 1511, which remain energized in circuits hereinbefore traced.

The multi-contact relay 1513 of the translator 1503 is now operated in a circuit from 75 battery, through the winding of said relay, lower front contact of relay 1508, inner lower back contact of relay 1514, contact of relay 1506, to the grounded conductor 1512. Relay 1515 is operated in a circuit from 80 battery, through the winding of said relay, lower front contact of relay 1509, inner back contact of relay 1516, thence to ground over conductor 1512. With relays 1513 and 1515 85 operated, a circuit is closed for operating the relay 1600. The relay 1600 is individual to the group of trunks outgoing from the trunk selector switches 300 to the final switches 400 in the local office. The circuit for this relay may be traced from battery, 90 through the winding thereof, thence through the distributing frame 1518, contact of relay 1513, contact of relay 1515, conductor 1519, front contacts of relays 1510 and 1511, back contacts of relays 1520 and 1521, to 95 ground over conductor 1512 as previously traced.

Since relay 1600 represents a local trunk group into which the connection is to be extended, this relay may also be employed to 100 give the sender certain class information to the effect that the call is a local one.

Relay 1600 in operating, causes the operation of relay 1609 by means of a circuit from battery, through the winding of the 105 latter relay, through the distributing frame 1618, to ground at the contact of relay 1600. Relay 1609 causes the operation of the class relay 806 in the sender to record in said 110 sender the fact that a local call is being made. The circuit may be traced from battery, through the winding of relay 806, conductor 815, through the connector 1300, conductor 1312, inner left contact of relay 1609, to ground at the inner left contact of relay 115 1608. The class relay 806 locks through its inner left contact, thence through the right back contact of relay 816, to the grounded conductor 811. With relay 806 operated, a circuit is completed for operating the relay 120 1614. This circuit may be traced from battery, through the right winding of relay 1614, outer left front contact of relay 1609, right back contact of relay 1615, conductor 1620, outer left back contact of relay 2001, 125 conductor 2033, through the connector 1300, conductor 1313, conductor 900, to ground at the outer left contact of relay 806. Relay

1614 locks through its left winding and contact, conductor 1621, to ground at the outer left contact of relay 1611.

The relay 1614 serves to open the start circuit for the frame connector 2100 to prevent the association of the marker with the district frame 205, inasmuch as the marker is about to be released. This start circuit will be described hereinafter. Relay 1614 10 operates the marker release relay 1613 in a circuit which may be traced to ground at the back contact of relay 1604. Relay 1613 causes the release of the marker from the sender.

15 *Release of the marker.*—When relay 1613 operates, it operates the release relay 804 in the sender by means of a circuit traceable from battery, through the winding of relay 804, normal contact of said relay, conductor 817, through the connector 1300, conductor 1314, inner left back contact of relay 1612, front contact of relay 1613, to the grounded conductor 1621. Relay 804 energizes and locks through its make contact 20 to the grounded conductor 810. Relay 804 opens both the operating and locking circuits of relay 805. This latter relay releases. When relay 805 releases, it removes battery potential from conductor 1408, thereby releasing relays 1406 and 1405 of the sender connector 1300 and relay 1611 in the marker. Relays 1405 and 1406 cause the release of the remaining energized relays associated with the connector 1300, including the relays 1301 25 and 1306, whereby the sender is completely disconnected from the marker.

Relay 1611 in the marker removes ground from the holding conductors, and relays 1609, 1614, 1613 and 1600 and the energized relays shown in Fig. 15 are released.

40 *Reassociation of the sender with a marker.*—After the numerical record has been recorded on the registers of the sender, the said sender is automatically associated with an idle marker which may be a marker previously used or another one. It will be assumed that the same marker is taken for use a second time. When the control sequence switch 520 reaches position 8 following the registration of the units digit, relay 801 is operated in a circuit from battery through the winding thereof, right contact of relay 800, outer right contact of relay 805, outer right front contact of relay 806, conductor 819, right contact of relay 902, conductor 903, upper right contact of spring 551, conductor 647, conductor 820, inner right front contact of relay 804, outer right back contact of relay 808, conductor 809, to ground at the upper contact of sequence switch spring 550. It will be noted that the relay 902 is in an operated condition at this time due to a circuit from battery through the right winding of said relay, to ground at the inner right contact of relay 806. Relay

801 closes an obvious operating circuit for relay 802 and both these relays lock through their inner front contacts and the left contact of relay 808 to the grounded conductor 811.

The sender connector 1300 is now operated to connect the sender to the marker. For this purpose the relay 1406 is energized in a circuit traceable as hereinbefore described over the conductor 1408, thence 70 through the outer left contact of relay 801 and the inner left contact of relay 802, to battery. Following the operation of the sender connector 1300, the office record is again transferred to the registers 1500, 1501 80 and 1502 for the purpose of setting the translator 1503. The setting of the translator on this occasion, however, is of no purpose, since the call is a local one.

Immediately that the sender connector 1300 85 operates, a circuit is closed for operating the relays 1608 and 1604, due to the fact that the class relay 806 in the sender was operated the first time the sender was attached to the marker. This circuit may be traced from 90 battery through the winding of relay 1604, and from battery through the winding and normal contact of relay 1608, in parallel, thence through the outer left back contact of relay 1609, right back contact of relay 1615, and thence over conductor 1620 as previously described to ground at the outer left contact of relay 806.

The circuit for relays 1608 and 1604 is 100 closed before the record is traceable to the marker and before the group relay 1600 has time to operate and cause the operation of relay 1609. Relay 1608 locks through its inner right front contact, outer left contact of relay 1610, to ground at conductor 1621, the relay 1611 being operated as hereinbefore described. Immediately that the relay 1608 operates, it removes ground from conductor 1512, thereby rendering the translator 1503 ineffective to cause the operation 105 of one of the group relays 1600. Therefore, the relay 1609 is again operated.

110 *Transfer of the numerical record from the sender to the marker.*—Upon the second association of the sender with the marker, the numerical record on the registers 1100, 1101, 1102 and 1200 is traceable to the corresponding registers 1700, 1701, 1702 and 1703 in the marker. In a manner similar to that in connection with the office code register relays in the marker, some of the relays of the numerical registers 1700, 1701, etc., are operated in circuits from battery through their windings, thence over the conductors conventionally represented by the lines 1710, 1711, 1712 and 1713 through the connector 1300, thence through back contacts of the non-operated register relays in the sender, conductor 1113, through the connector 1300, conductor 1316, left back con- 120

130

tact of relay 1708, conductor 1714, conductor 1817, back contact of relay 1818, conductor 1819, outer right back contact of relay 2001, conductor 2035, inner right contact of relay 1609, middle right front contact of relay 1608, conductor 1622, right back contact of relay 1610, to the grounded conductor 1621. The remainder of the relays of the marker registers which correspond to the operated relays in the sender, are operated over circuits leading through the front contacts of the sender register relays, to ground. When all of the relays in the marker registers have operated, relay 1707 is energized in a series circuit traceable through contacts of all the register relays to ground. Relay 1707 locks to the grounded conductor 1714 and causes the operation of relays 1708 and 1709. Relay 1708 opens the operating circuits of all relays in the registers 1700, 1701, etc., except relays 1715, 1716, 1718, 1719 and 1720, which correspond to the operated relays in the sender registers.

With the numerical record established in the marker, the translator 1704 is operated to determine the selection of the proper one of the line test connectors shown in Fig. 22 which is individual to the final group of four hundred lines containing the called line 401. The operation of the translator 1704 is determined by the thousands register 1700 and the hundreds register 1701. The multi-contact relay 1706 is operated in a circuit from battery through its winding, lower front contact of relay 1716, inner lower contact of relay 1721, conductor 1722, outer right contact of relay 1709, to ground over conductor 1714.

With relay 1706 operated, a start circuit is completed for operating the relay 2207, which is individual to the marker shown in the particular connecting device 2200 having access to the proper line test connector. This circuit may be traced from ground through the left back contact of relay 2212, left winding of relay 2207, conductor 2219, connecting rack 1724, contacts of relay 1706, conductor 1725, back contacts of relays 1726 and 1727, upper front contact of relay 1715, upper back contact of relay 1728, conductor 1729, inner left contact of relay 1709, to battery.

Relay 2207 in operating, completes a locking circuit for itself through its right winding and contact, back contact of succeeding relays such as relay 2220, winding of relay 2212, to ground. Relay 2212 operates and closes a circuit for operating the multi-contact relay 2205. This circuit may be traced from battery through the winding of the latter relay, contacts of relays 2207 and 2212, to ground. Relay 2205 connects the various leads from the marker to the line testing mechanism. Relay 2207 also causes the op-

eration of relay 1928 in a circuit from battery through the winding of the latter relay, conductor 1929, outer left contact of relay 2207, to ground at the contact of relay 2212. Relay 1928 causes the operation of relay 1916 in an obvious circuit. Due to the time required for recording the record in the marker and operating the translator 1704, the relay 1916 does not become operated until after a sufficient time has expired for recording the district frame test on the relays shown in Fig. 19. The manner in which this frame test is recorded will be described in detail hereinafter.

Since there are four hundred lines in the final choice, four multiple contact relays 2215, 2216, etc., are provided in the device 2201 and one of these is operated dependent upon the hundreds digit. Assuming that relay 2215 is the one operated, the circuit therefor may be traced from battery through the winding of said relay, contact of relay 2205, conductor 2221, contacts of relay 1706, to the grounded conductor 1817.

Since only the register relay 1720 of the units register is operated, a circuit is closed as follows for operating the units relay 1815, battery through the winding of relay 1815, conductor 1732, lower inner back contact of relay 1733, lower outer front contact of relay 1720, lower inner back contacts of relays 1734 and 1735, right inner contacts of relay 1709 to grounded conductor 1714. There are ten of these units relays, only a part of which are shown.

For the particular setting assumed for the tens register 1702, a circuit is closed for operating the multi-contact relay 2213 (which is one of ten relays) from battery through the winding of said relay, contacts of connector 2200, conductor 2222, upper front contacts of relays 1719 and 1718, upper back contact of relay 1730, to ground at the outer left contact of relay 1709.

A test is now made to determine whether or not the called subscriber's line 401 has full potential applied thereto through the cut-off relay. This test is made by means of a circuit including relay 1807. If the line is idle, there will be full battery potential thereon through the winding of a cut-off relay similar to the relay 102 shown in connection with the calling line 100. In this case, the relay 1807 receives sufficient current to operate. If the line is busy, however, the source of battery through the cut-off relay is connected to ground, and hence the test relay 1807 being shunted does not receive sufficient current to operate.

Before continuing with the effect of testing the called line, a description will first be given of the operation of the district frame connector 2100 and also of the testing equipment shown in Fig. 20 for testing the trunks.

Association of the marker with the district switch through the district frame connector.—It is now necessary to connect the selected marker with the particular one of the several district selectors 205 which has been taken in use for the extension of this particular call. This is accomplished by selectively operating the district frame connector 2100 under the control of a group of test relays 1950. These relays, some of which are marginal and others sensitive, are operated in different combinations dependent upon the manner in which the connecting block 246 is wired at the district switch involved and also dependent upon whether the relay 227 is connected to battery or ground.

Immediately that the sender is associated with the marker the second time, assuming the connecting block 246 is wired to direct ground without resistance, a circuit is closed as follows: Ground through the connecting block 246, right back contact of relay 242, conductor 247, contact of switch 501, conductor 552, contact of relay 508, contact of switch 502, conductor 553, inner right back contact of relay 628, conductor 649, through the connector 1300, conductor 1318, left contact of relay 1915, left back contact of slow-operating relay 1920, winding of marginal relay 1918, winding of sensitive relay 1911, to ground. Since this circuit has the same terminal of battery connected to both ends thereof, the relays 1911 and 1918 fail to operate. It will be noted that a circuit is at this time closed for relay 1920 at the inner left contact of the ground supply relay 1611. The relay 1290 however, being slow to operate, does not attract its armatures following the closure of its circuit by the relay 1611 until an interval has expired sufficient to allow the closure of the above traced test circuit.

After the proper interval has expired, relay 1920 operates its armatures and a new test circuit is now completed from ground through the connecting block 246 and thence as above traced through the left front contact of relay 1920, winding of marginal relay 1919, winding of relay 1912, to battery. This time battery potential being included in the circuit, relay 1912 operates and relay 1919 also energizes, inasmuch as the resistance 248 is not included in the circuit. Relay 1919 closes an obvious circuit for the relay 1917. Relay 1917 locks through its inner right armature, thence over conductors 1931 and 1624, outer left contact of relay 1612, back contact of relay 1613, to the grounded conductor 1621.

Assuming the relay 227 is connected with battery, another test circuit is completed from battery through the winding of said relay, inner upper back contact of relay 217, conductor 250, contact of switch 501, con-

ductor 554, inner left contact of relay 508, contact of switch 502, conductor 555, outer right back contact of relay 648, conductor 650, through the connector 1300, conductor 1319, right contact of relay 1915, back contact of relay 1916 (the latter relay not being operated at this time), inner right back contact of relay 1920, left winding of relay 1914, to ground. Relay 1914 operates in this circuit and locks through its right winding, 75 to ground over conductor 1931. Relay 1914 closes an obvious circuit for relay 1932. When, a moment later, relay 1920 operates as above explained, another test circuit is completed from battery through the winding of relay 227, thence as above traced, through the inner right front contact of relay 1920, winding of test relay 1913, to battery. The same potential of battery being connected at both terminals of this circuit, relay 1913 fails 85 to operate.

With the test relays 1950 operated in the combination explained, a start circuit is completed for operating the relay 2103, individual to the marker shown, at the particular 90 district frame connector 2100 having access to the group of district frames containing the required district 205. This circuit may be traced from ground through the right back contact of relay 2104, right winding of 95 relay 2103, conductor 2110, inner right contact of relay 1932, outer right front contact of relay 1917, contact of relay 1912, conductor 1933, outer left contact of relay 1614, conductor 1625, outer right contact of relay 100 1920, contact of relay 1928 (the latter relay having operated by this time), to battery. Relay 2103 immediately locks in a circuit through its left winding and contact, contacts of similar succeeding relays, through 105 the winding of relay 2104, to ground. Relay 2104 operates and prevents the operation of another relay similar to relay 2103. The multi-contact relay 2102 is now operated in a circuit from battery through its winding, 110 contacts of relays 2103 and 2104, to ground.

At the time relay 227 operates in the above traced test circuit, it causes the operation of the multi-contact relay 2102 which is individual to the particular district selector 115 205. This circuit may be traced from battery through the winding of relay 2101, to ground at the outer right contact of relay 227. With relays 2101 and 2102 both operated, the various circuits are extended 120 through from the marker to the district selector switch 205.

Since the call being extended is a local one, the repeating coil and local battery shown in Fig. 2 will be used. Accordingly, 125 it is necessary to operate the relay 214. The circuit for this relay may be traced at this time from battery, through the winding thereof, inner left contact of relay 223, conductor 257, through the connector 2100, con- 130

ductor 2124; to ground at the middle left contact of relay 1608.

Relay 227 now has a locking circuit closed traceable from battery through its winding and inner left contact, conductor 251, through the connector 2100, conductor 2111, outer left back contact of relay 1913; inner left contact of relay 1914; to ground. Relay 227 closes an obvious circuit for relay 223. Relays 217 and 222 are now operated in circuits from battery through the lower winding of relay 217 and through the winding of relay 222 in parallel; outer right contact of relay 223, conductor 252, to the connector 2100 to ground. Relay 217 locks through its lower winding and front contact; make contact of relay 212, outer left contact of relay 209, inner right back contact of relay 207, to the grounded conductor 238. Relay 222 also locks in a circuit through the front contact of relay 217 to ground as described.

Testing for an idle path.—The marker having been associated with the district frame and also with the group of trunks leading from the trunk connector stage to the proper final group, a test is now to be made to ascertain an idle trunk leading from the district switch 205 to an incoming switch frame 300 in which appears an idle trunk 306 leading into the proper final group. For this purpose, it will be assumed that the group of trunks outgoing from the trunk connector stage consists of 66 trunks. As was hereinbefore pointed out, there will be two of these trunks appearing in each of the 33 different trunk connector frames. In the drawing, one complete trunk 306 is shown and also a separate trunk 307 is diagrammatically illustrated. These two trunks are shown to be appearing in the same frame. Obviously, there will be two other trunks appearing in each and every other of the remaining 32 trunk frames.

There are, as previously explained, 99 trunks 229 outgoing from the district frame 205 to the various trunk connector frames. There are also assumed to be three of these trunks leading separately to each trunk connector frame. It will further be assumed that the particular trunk 229 illustrated is the first one of a group of three leading from the district frame 205 to the particular trunk connector frame illustrated in Fig. 3. In order to test the condition of this trunk, a circuit is completed from battery through the right winding of test relay 2010, back contact of relay 2037, conductor 2038, through the connector 2100, to the sleeve conductor 2112 of the trunk 229. If this trunk is idle, the test relay 2010 remains inert. In a similar manner, the second trunk of the group of three is tested by means of a circuit from battery through the right winding of the relay 2012 and thence to the sleeve conductor of such trunk. Like-

wise, the third trunk is tested by means of the test relay 2015. Similarly, each group of three trunks leading from the district frame 205 to the other trunk connector frames, is also tested by the test relays 2000. 70

At the same time that the trunks leading from the district frame are being tested, a test is made of each pair of trunks 306 and 307 outgoing from each of the 33 trunk connector frames to the proper final group. The particular trunk 306 is tested by means of a circuit from battery through the winding of relay 2022, left back contact of relay 2023, conductor 2039, through the connecting device 2200, conductor 2223, outer right back contact of relay 304, to the sleeve conductor 417 of the trunk 306. The second trunk 307 is tested by means of a circuit from battery through the winding of relay 2028, left back contact of relay 2029, conductor 2040, connector 2200, conductor 2224, thence to the sleeve conductor of the trunk 307. If it is assumed that the trunk 306 is idle, then the test relay 2022 remains deenergized. 90

At the time the district frame connector 2100 operates, the preference relay 2024 is energized by means of a circuit from battery through the winding of said relay, conductor 2041, through the connector 2100, to ground. The connector 2100 being associated with a particular district frame, causes the operation of preference relay 2024 whenever a call is to be extended involving one of the districts on this frame. The purpose of the relay 2024 is to start the test circuit at a particular point in the chain relays 2000. Another preference relay 2027 is shown which may be operated whenever some other district frame connector 2100 is taken into use. This preference relay will cause the start circuit to be closed at a different point in the chain of relays. The purpose of these preference relays (there being one for each district frame), is to provide a distribution by starting the testing circuit at different points in the relays 2000 depending upon the district frame being used. The preference relays are made slow operating in order to allow time for the test relays 2000 to become stabilized before closing the start circuit. 100 105 110

With relay 2024 operated, the start circuit is closed traceable from ground through the outer left contact of relay 1608, conductor 1627, left contact of relay 2002, conductor 2042, outer left front contact of relay 2024, left back contact of test relay 2010 (this relay being deenergized), winding of relay 2037, to battery. If the second trunk 307 had been busy, the test relay 2028 would have operated. Accordingly, when relay 2037 operates, it closes an energizing circuit for the relay 2023 traceable from battery through the winding of the latter relay, outer right front contact of relay 120 125 130

2028, to ground at the left contact of relay 2037. Relay 2023 at its left front contact, applies ground potential to the conductor 2039 to render the trunk 306 non-selectable. The relay 2028 in operating locks through its winding and inner right contact, outer right contact of relay 2024, to ground at the right contact of relay 2002. Relay 2037 at its right back contact opens the 10 circuit through the right winding of test relay 210 to prevent the subsequent operation of this relay.

The connecting trunk 229 thus having been determined as the proper one to be used for this connection, a selectable condition is now placed upon the sleeve conductor thereof in order that the switches 205 and 203 may find the terminals of this trunk when they are driven upwardly over their 20 contact banks. For this purpose, a circuit is completed from battery through the right front contact of relay 2037, conductor 2038, thence to the sleeve conductor 2112 of the trunk 229.

25 *Association of the marker with the trunk frame through the trunk frame connector.*—Since the test has been made and an idle path through the district and trunk connector stages has been ascertained, it is now known which particular trunk frame is to be involved in the extension of the connection. Therefore, the marker must now be connected to this particular trunk frame through the agency of a trunk frame connector 2105. There will be one of these trunk frame connectors for each trunk frame, for example, and whenever a particular trunk frame is being used, the individual connector will be employed.

40 The relay 2108, which is individual to the particular marker shown, is operated in a circuit which may be traced from ground through the back contact of relay 2109, right winding of relay 2108, conductor 2113, inner right contact of relay 2023, conductor 1933, and thence to battery as heretofore traced, through the contact of relay 1928. Relay 2108 operates and locks through its left winding and front contact, and thence 45 through back contacts of similar succeeding relays which are individual to other markers, to ground through the winding of relay 2109. Relay 2109 operates and opens the operating circuit to prevent the operation 50 of other relays similar to the relay 2108. Relay 2108 closes an obvious circuit for relay 2107. The relay 2107 operates to connect the various leads from the marker through to the trunk connector frame shown 55 in Fig. 3.

60 *Testing the called subscriber's line.*—A description will now be given of the manner in which the relay 1807, previously referred to, makes a test to ascertain whether or not full 65 battery potential is applied through the

winding of the called line cut-off relay. The circuit for this purpose may be traced from ground through the contact of relay 1806, right winding of relay 1807, conductor 1820, left back contact of relay 1804, left contact 70 of units relay 1815, conductor 1821, through the connector 2200, connector 2201, connector 2203, conductor 2225, to the sleeve conductor 414 of the called line 401. If full battery potential exists on the sleeve conductor of the called line, relay 1808 operates and locks through its left winding and contact to the grounded conductor 1930. 75

80 After the test has been made to select an idle path through the district and trunk connector stages, the relay 1804 is operated in a circuit from battery through the winding thereof, conductor 1822, to ground at the outer right contact of relay 2023. Relay 1804 closes an obvious circuit for the slow-operating relay 1805. Before relay 1805 has 85 time to operate, a test is made to ascertain the busy or idle condition of the called line 401. For this purpose, a circuit is closed for the test relay 1808 and may be traced from battery through the inner right contact of relay 1801, right winding of relay 1808, outer right back contact of relay 1805, left front contact of relay 1804, left front contact of relay 1815, and thence over conductor 1821 as previously traced, to the sleeve conductor 414 of the called line. If the called line is busy, a ground potential will exist on the sleeve conductor and the test relay 1808 operates 90 in response thereto. Assuming, however, 100 that the line is idle, the test relay 1808 remains deenergized.

95 *Operating the selector switches.*—The apparatus is now in condition for starting the district selector, trunk selector and final selector in operation to establish the connection. When the connecting device 2105 has 105 been operated, relays 1900, 1905, 1907, 1915 and 1823 are energized. The circuit for this purpose may be traced from battery, through 110 the winding of relay 1907 and in parallel therewith through the winding of relay 1905, contact of relay 1906, right back contact of relay 1904 and in parallel therewith through the winding of relay 1900, contact of relay 115 1901, right back contact of relay 1904 and in parallel therewith from battery, through the winding of relay 1823, contact of relay 1824, conductor 1825, outer right contact of relay 1608, conductor 1628, right back contact of relay 1904 and in parallel therewith through the winding of relay 1915 thence to the common conductor 1935, outer contact of relay 2108 to ground at the front contact of relay 2109. Relay 1907 being slow to operate 120 does not attract its armatures until after an appreciable interval has expired.

125 The updrive power magnet 225 of the district selector switch is now energized in a circuit from battery, through the winding 130

thereof, inner right back contact of relay 222, middle right contact of relay 227, conductor 310, through the connector 2100, conductor 2115, outer left contact of relay 1900, conductor 1936, conductor 1826, conductor 1827, inner right contact of relay 1807, left back contact of relay 1801, inner right contact of relay 1805 to ground at the right back contact of the line test relay 1808. Magnet 225 causes the brush shaft to move upwardly, trailing the brushes over the terminals of the bank. When the brushes reach the set of terminals in which appears the connecting trunk 229, a circuit is completed from battery in Fig. 20 through the right front contact of relay 2037, thence over conductor 2308 as hereinbefore traced to the sleeve conductor 2112 of the trunk 229, test brush of the switch 205, conductor 253, outer left front contact of relay 223, conductor 254, through the connector 2100, conductor 2116, winding of test relay 1901, inner right contact of relay 1900, conductor 1937 to the grounded conductor 1931. The test relay 1901 operates in this circuit and opens the original circuit of relay 1900. Relay 1900, however, remains operated momentarily in a locking circuit traceable from battery, its winding and inner left contact, conductor 1938, through the connector 2100, conductor 2117, through the inner right contact of relay 227, commutator segment 255, brush 256 to ground. When the brushes of switch 205 are accurately centered on the terminal, this holding circuit is opened at the commutator 255 and relay 1900 releases, thereby opening the circuit of power magnet 225. The switch then comes to rest.

At the time relay 2023, associated with test relays 2000, is operated, energizing circuits are closed for relay 303 associated with the trunk connector and relay 408 associated with the final selector. The circuit for relay 303 may be traced from battery, through the winding thereof, normal contact of relay 305, conductor 311, commutator segment 415, and its associated brush, thence through commutator segment 416, conductor 417, outer right back contact of relay 304, conductor 2223, thence as previously traced to ground at the left front contact of relay 2023. Relay 303 operates and locks through its winding and inner left contact, through the connector 2105, conductor 2118, thence to ground over conductor 1937. Relay 303 extends conductors 314 through to the particular trunk connector switch 300 to which such relay is individual. Conductor 313 is common to a plurality of switches on the same trunk connector frame and is thus extended through the contacts of the individual relay 303 to the particular switch involved in the connection.

The operating circuit for relay 408 may be traced from battery, through the winding

thereof, commutator segment 418 and its associated brush, thence over commutator segment 416 as previously traced to ground at the contact of relay 2023. Relay 408 locks through its inner right contact, through connector 2200, conductor 2227 to ground at the right middle contact of relay 1907. The circuit for operating the power magnet 301 of the trunk connector switch 300 may be traced from battery, through the winding of said magnet, outer left back contact of relay 304, outer right contact of relay 303, conductor 313, conductor 2105, conductor 2120, outer left contact of relay 1905 to ground over conductor 1936 as previously traced.

As soon as the brushes of the connector 300 reach the terminals of trunk 229, the sleeve conductor 2112 which has battery potential thereon as above explained, is extended to the test brush of the switch 300, outer left contact of relay 303, connector 2105, conductor 2121, winding of relay 1906, to ground at the outer right contact of relay 1905. Relay 1906 operates and opens the original circuit of relay 1905. This latter relay, however, remains locked temporarily in a circuit from battery through its winding and left contact, conductor 2122, connector 2105, middle left contact of relay 303, centering commutator 315 and its associated brush, to ground. When the brushes of the switch 300 are accurately centered on the terminals, the commutator 315 is disengaged by its brush and relay 1905 becomes released to open the circuit of the power magnet 301, whereupon the brush shaft of the switch 300 comes to rest. Relay 1906 releases following the de-energization of relay 1905, as did the relay 1901 following the release of relay 1900.

A description will now be given of the operation of the final selector switch 400. At the time the translator 1704 is operated following the receipt of the numerical designation in the marker, the proper one of the trip magnets of the final switch 400 is operated. In the case assumed, there are four sets of brushes on each switch, and accordingly there are four trip magnets. Two of these, 410 and 422, are shown. Assuming the magnet 410 is the one for tripping the set of brushes illustrated which have access to the called line 401, this magnet is energized by means of a circuit from battery through its winding, conductor 423, connector 2200, conductor 2231, contact of relay 1706, conductor 1731, to ground at the outer left contact of relay 1801. The magnet 410 on energizing prepares to trip the associated set of brushes on the first upward movement of the switch.

The up-drive power magnet 411 for driving the brushes upwardly is energized in a circuit from battery through the winding thereof, outer left back contact of relay 409, inner left contact of relay 408, connector 130

2200, conductor 2228, outer left front contact of relay 1823, thence over conductor 1827 as previously traced, to ground at the contact of test relay 1808. As soon as the 5 brushes of the final switch 400 have reached the terminals of the called subscriber's line 401, a circuit is closed as follows for operating the test relay 1824: Ground through the winding of said relay, outer right front 10 contact of relay 1823, conductor 1829, through the connector 2200, conductor 2229, outer right front contact of relay 408, through the test brush of the switch 400 to the sleeve conductor 414 of the called subscriber's line, and thence to battery as previously traced. The relay 1824 operates in this circuit and opens the original operating 15 circuit of relay 1823. Relay 1823, however, remains temporarily locked by means of a circuit from battery, through its winding and inner right contact, conductor 1830, connector 2200, conductor 2230, middle right contact of relay 408, through the centering commutator and its associated brush, thence 20 to ground through the commutator segment 421. When the brushes of the final switch have accurately centered upon the terminals of the called line, the commutator 420 is disengaged by its brush and relay 1823 releases, in turn releasing relay 1824 and also 25 opening the circuit of the power magnet 411. Thereupon the brushes of the final switch come to rest.

It will be noted from the foregoing description that the district switch 205, trunk selector 300, and the final selector 400 are all operated at substantially the same time, and it is unnecessary that one switch in the train should wait for a preceding switch to 40 take a setting before it commences with the operation.

Following the setting of the switches, relay 1904 is energized in a circuit from battery through its winding, outer right contact of relay 1900, inner right contact of relay 1905, to ground at the left contact of relay 1907.

Returning to the point where the relay 1915 operated, it will be noted that this relay 50 causes the release of the frame test relays 1912 and 1919. Relay 1912 opens the holding circuit of relays 2103 and 2104 and these relays release, releasing in turn the multi-contact relay 2102. Thereby the marker is 55 disassociated from the district frame 205 and relays 227 and 223 become released. Relay 227 opens the circuit of multi-contact relay 2101.

Returning now to the point where the 60 relay 1904 is operated following the setting of the switches, this relay closes an obvious circuit for the slow-operating relay 1903. Before relay 1903 attracts its armatures and while relay 1904 is operated, a circuit is completed for operating the relay 305. This

circuit may be traced from battery through the winding of the latter relay, contact of relay 303, connector 2105, conductor 2123, right back contact of relay 1903, left contact of relay 1904, to the grounded conductor 70 1937. Relay 305 locks in a circuit from battery through its winding and inner right front contacts, thence through the sleeve brush of the switch 300, sleeve conductor 2112 of the trunk 229, sleeve brush of the 75 district switch 205, conductor 253, outer left back contact of relay 223, outer left back contact of relay 224, to ground at the outer left contact of relay 222.

Upon the operation of relay 305, the relay 1614 in the marker is re-operated in a circuit traceable from battery through the right winding of relay 1614, conductor 1630, right front contact of relay 1903 (the latter relay having operated), thence over conductor 85 2123 through the inner right front contacts of relay 305, to the grounded sleeve conductor 2112. Relay 1614 locks through its left winding to ground at the holding relay 1611. It may be noted at this point that the relay 1831 has been operated in a circuit from battery through the winding thereof, inner right front contact of relay 1907, conductor 1939, outer left back contact of relay 1823, to ground over conductor 1827 as previously traced. Hence a circuit is completed for operating the relay 1818. This circuit may be traced from battery through the winding of said relay, contact of relay 1831, outer right back contact of relay 1800, outer 90 right front contact of relay 1805, left front contact of relay 1804, contact of relay 1815, conductor 1821, connector 2200, connector 2201, connector 2203, conductor 2225, to the sleeve conductor 414, thence through the test device of the switch 400, outer right front contact of relay 408, conductor 2229, through the connector 2200, conductor 1829, to ground at the outer right back contact of relay 1823. It may also be noted that the 95 ground potential supplied for this circuit serves to render the line 401 busy. With relay 1818 and relay 1614 operated, the circuit is closed for operating the marker release relay 1613. This circuit may be traced from battery through the winding of relay 1613, middle left contact of relay 1614, conductor 1629, to ground at the left contact of relay 1818.

The release of the marker.—The marker may now be released since it has completed its function in controlling the setting of the switches. At the time relay 1614 operates, it opens the circuit of relays 2109 and 2108, whereby these relays become released and open the circuit of relay 2107, which in turn disconnects the marker from the trunk selector.

At the time the relay 1818 operates, it removes ground from conductor 1714, causing 130

the release of the translator shown in Fig. 17. The release of the translator in turn causes the release of relays 2207 and 2212, which in turn cause the release of multi-contact relay 2205. Thus the marker is disassociated from the trunk selector and final switches.

The operation of relay 1613 removes ground potential from the conductor 1624, whereby the various energized relays in Fig. 19 and in other parts of the marker are released. The test relays shown in Fig. 20 are also released at this time.

While the release relay 1613 is in its operated condition, and before the marker is disassociated from the sender, a circuit is closed for operating the relay 800 in the sender, traceable from battery through the winding thereof, outer left contact of relay 802, outer left contact of relay 805, front contact of relay 804, conductor 817, and thence as previously traced through the sender connector 1300, conductor 1314, left back contact of relay 1612, front contact of relay 1613, to ground at the contact of relay 1611. Relay 800 locks through its left front contact to the grounded conductor 810. Relay 800 causes the release of relay 801. Relay 801 at its outer left contact opens the circuit of relays 1406 and 1405, and these relays in turn cause the release of the sender connector 1300. The removal of battery potential from conductor 1408 and the release of the connector 1300, cause the release of holding relay 1611 in the marker. Relay 1611 removes ground potential from the various conductors and all energized relays in the marker now become released.

Release of the sender and the sender selector.—Relay 801 in releasing causes the release of the sender by operating the sender release relay 603. The circuit of relay 603 may be traced from battery through the winding thereof, conductor 651, conductor 711, outer right contact of relay 802, to ground at the right back contact of relay 801. Relay 603 locks in a circuit from battery through its winding and inner left contact, thence over conductor 652, conductor 653, to ground at the upper right contact of sequence switch spring 543. Relay 603 at its outer right contact completes a circuit through the contact 556 for driving the sequence switch 520 through its succeeding positions into its normal position 1. in order to bring about a release of the sender. Relay 603 at its outer left contact opens the circuit of relays 604, 512 and 212, permitting these relays to release. Relay 604 removes ground from the various holding conductors to permit the release of the operated relays in the sender control circuit.

The release of relay 512 causes the deenergization of relay 508, and the sender selector 500 may now be taken for use in connec-

tion with other calls. Considering the switch 501, a brief explanation will be given of the manner in which the same operated in a downward hunting movement to search for a calling link circuit.

After the brushes of the switch have been driven to the upward part of the bank, the commutator brush engages the segment 557, and a circuit is closed from battery through both windings of relay 509 to ground through the segment 557. Relay 509 operates and locks to its inner right contact. Relay 509 at its middle left contact closes the circuit for the down-drive magnet 511, which causes the brushes to move downwardly over the terminal bank. When the switch again reaches its lower normal position, the commutator brush engages the segment 558 and a circuit is completed from battery through the left winding of relay 509, outer right contact of said relay, directly to ground through the segment 558. The left winding of relay 509 is so arranged that it will not create sufficient flux to hold the relay 509 operated. Therefore, the relay releases, opens the circuit of the down-drive magnet 511, and prepares a circuit for the up-drive magnet 510 as previously explained.

When relay 212 releases in the link circuit, the talking circuit extending from the calling subscriber's line to the repeating coil 213 is completed and the supervisory relay 215 which is included therein is now held operated in series with the calling line. Relay 212 at its inner lower contact opens the holding circuit of relays 217 and 222, and these relays release. A ground potential is maintained on the sleeve conductor of the trunk 229 by means of a circuit traceable over conductor 253, outer left back contact of relay 223, outer left contact of relay 224, inner left contact of relay 218, middle left back contact of relay 211, outer right contact of relay 206, inner right back contact of relay 207, to the grounded conductor 238.

Ringing the called line.—A description will next be given of the manner in which ringing current is applied to the called subscriber's line 401. At the time the final selector 400 first moves off normal, the relay 407 is operated in a circuit from battery through its winding, left contacts of relays 405, 402 and 403, right contacts of relay 409, conductor 424, to the grounded commutator segment 425. Relay 407 operates the relay 402 in a circuit from battery through the winding of the latter relay, to ground through the right contacts of the relay 407.

Relay 402 locks in a circuit, through its winding and front contact, normal contact of relay 403, normal contact of relay 409, to the grounded conductor 424. Relay 402 opens the circuit of relay 407, but this latter relay being slow to release does not retract

its armatures until the district selector switch which is now operating has reached the selected trunk and placed a ground potential upon the holding conductor 311. 5 As soon as conductor 311 is grounded, relay 405 operates in a circuit from battery, through its winding, back contact of relay 406, to ground on conductor 311. When relay 407 now releases, it does not close a circuit for the down-drive power magnet 412.

When relay 405 operates, the ringing relay 403 is energized in a circuit from battery, through its winding, outer right front contacts of relays 405 and 402, thence over 15 the tip conductor of the connection, through the tip brush of the district switch 205, outer right back contact of relay 224, uppermost contact of relay 217, upper right winding of the repeating coil 213, upper 20 front contact of relay 214, to ground. Relay 403 completes a locking circuit for itself from battery, through the winding thereof, outer right front contact of relay 405, contact of the ringing trip relay 404, 25 inner left front contact of relay 403, normal contact of relay 409, to the grounded conductor 424. Relay 403 also causes the release of relay 402.

The ringing circuit may now be traced 30 from the ringing source 426, through the winding of the ringing trip relay 404, outer left front contact of relay 403, thence over the ring of the called subscriber's line, and returning over the tip conductor to ground 35 through the right front contact of relay 403. When the called subscriber answers, relay 404 operates in the well known manner and opens the holding circuit of relay 403, whereby the latter relay releases. Relay 403 40 opens the ringing circuit and completes the tip and ring conductors of the talking circuit through to the subscriber's line.

When the connection is thus completed through to the called subscriber's line, the 45 call supervisory relay 216 is operated in a circuit from battery, through the inner lower contact of relay 214, lower winding of relay 216, lower front contact of relay 214, lower right winding of the repeating coil 213, thence over the ringing conductor of 50 the connection to the called subscriber's line, and returning over the tip conductor through the upper right winding of the repeating coil 213, to ground at the upper 55 front contact of relay 214.

Relay 216 operates and as soon thereafter as the interrupter 258 closes its lower contacts, the relay 220 is energized. The circuit for this purpose may be traced from 60 battery, through the lower contacts of interrupter 258, contact and right winding of relay 220, contact of relay 221, to ground at the front contact of supervisory relay 216. Relay 220 locks temporarily through 65 its right front contact and right winding,

As soon thereafter as the interrupter 258 closes its upper contacts, relay 221 is operated in a circuit from battery, through the upper contacts of said interrupter, left contact of relay 220, left winding of relay 221, 70 to ground. Relay 221 operates and opens the holding circuit of relay 220 and locks itself in a circuit through its right winding and contact, normal contact of relay 219, inner left contact of relay 218, and thence 75 as hereinbefore traced to the grounded conductor 238. After interrupter 258 opens its upper contacts, the relay 220 releases.

The connection is now in condition for 80 conversation.

Release of the connection.—When the conversation is ended, the subscribers replace their receivers on the switchhooks and the supervisory relays 215 and 216 become de- 85 energized. As soon thereafter as the power-driven interrupter 259 closes its upper contacts, the relay 219 is operated in a circuit from battery, through the contacts of said interrupter, contacts and right winding of relay 219, normal contacts of relay 222, inner 90 right front contact of relay 218, lower middle back contact of relay 217, contacts of relay 215, inner lower contact of relay 212, outer left contact of relay 209, thence as previously traced to the grounded conductor 95 238. Relay 219 locks through its right winding and right front contact.

Upon the next closure of the contacts of the interrupter 259, a circuit is closed as follows: battery, through the lower contacts of said interrupter, front contact and left winding of relay 219, and thence in parallel to the upper winding of relay 211. Relay 211 operates and relay 219 is held in this 100 circuit.

Relay 211 opens the circuit of relay 218 and this latter relay releases. Relay 218 in releasing, opens the circuit through the right winding of relay 219, and when thereafter the interrupter 259 opens its lower contacts, relay 219 becomes deenergized. During the time relay 219 is remaining energized following the release of the relay 218, the relay 221 is held in a circuit through its right winding and contact, outer left front contacts of relay 219, and thence to ground over conductor 238 as previously traced. When relay 219, however, releases, the relay 221 becomes deenergized.

The finder release relay 206 is now operated in a circuit from battery, through the winding thereof, conductor 260, outer left contact of relay 221, inner right back contact of relay 218, middle lower contact of relay 217, and thence as previously traced to 125 the grounded conductor 238. Relay 206 locks through its inner left contact. Relay 206 closes an obvious circuit for the down-drive power magnet 202 of the line finder switch 200. The brushes of the switch are there- 130

upon restored to normal. When the switch returns to normal, the brush 236 disengages the commutator 237 and the energized relays and magnets of the line finder are released.

- 5 When the relay 218 releases, relay 224 is operated in a circuit from battery through the left winding of the latter relay, outer right contact of relay 218, to ground through the commutator segment 261. Relay 224 10 locks through its left winding and contact to the commutator segment 260. Relay 224 closes an obvious circuit for the down-drive power magnet 226 which thereupon causes the restoration of the brushes of the district 15 switch 205. When the switch reaches its normal position, commutator segment 261 is disengaged and the circuit of relay 224 is opened to in turn open the circuit of the power magnet 226.
- 20 The release of the district selector removes ground potential from the sleeve conductor 2112 of the trunk 229, and relay 305 thereupon deenergizes. Relay 305 causes the operation of relay 304 in a circuit from battery, through the winding of the latter relay, left contact of relay 305, middle right contact of relay 303, through the off-normal segment 317 and its associated brush, to ground. Relay 304 locks directly to the 25 segment 317. Relay 304 at its outer right contact applies ground potential to the conductor 2223 to identify the switch as busy while restoring. Relay 303 also closes an obvious circuit for the down-drive power 30 magnet 302, and the trunk selector switch 300 is restored to its normal position. When the switch reaches normal, the circuit leading through the segment 317 is opened and relay 304 releases to again open the circuit of the magnet 302.

When ground potential is removed from the sleeve conductor 311, the relay 405 in the final switch releases. Relay 407 is now operated in a circuit from battery, through its 35 winding, normal contacts of relays 405, 402, 403 and 409, conductor 424, segment 425 and its associated brush, thence through the segment 421, to ground. Relay 407 re-operates the relay 402 in the manner described and relay 402 locks and also opens the circuit of relay 407. When relay 407 again releases, the relay 409 is operated in a circuit from battery, through the winding of the latter relay, inner right contact of relay 402, inner 50 right contact of relay 405, to ground at the back contact of relay 407. Relay 409 locks to the conductor 424. Relay 409 closes an obvious circuit for the down-drive power magnet 412, whereupon the brushes of the 55 final selector 400 are restored to their normal position. When the switch reaches normal, the commutator segment 425 is disengaged and the relay 409 is released to in turn open the circuit of the power magnet 412.

60 *Called line tests busy.*—If the called sub-

scriber's line is busy, relay 1807 fails to operate at the time the test is made. Subsequently, when the relay 1808 is placed in a test circuit as previously described, this relay now operates due to the fact that a ground potential exists on the sleeve conductor of the line. With relays 1807 and 1808 in this condition, relay 2001 operates in a circuit from battery, through the winding thereof, outer right back contact of relay 1807, to ground at the front contact of relay 808. Relay 2001 at its outer right back contact removes holding ground from the conductor 1714, causing the release of the translator and also the release of the connecting device 2200. The marker is thus disassociated from the switches of the final group.

65 Relay 1928, which operated with the connecting device 2200, is now held in a circuit traceable through the inner right contact of relay 2001, to ground. Relay 2001 at its outer left front contact causes the operation of relay 2002 in a circuit from battery, through the winding of the latter relay, outer left front contact of relay 2001, and thence over conductor 2033 as previously traced, to ground. Relay 2002 unlocks and causes the release of energized test relays 2000.

70 The operation of relay 2001 also causes the association of the marker with the trunk selector frames for the purpose of selecting an idle tone trunk and associating the same with the calling subscriber's line. One of these tone trunks 318 is illustrated. It may be assumed that there is one of these trunks 75 on each trunk selector frame. Accordingly, it will be necessary to test these 33 tone trunks in conjunction with the connecting trunks 229 incoming from the district frame 205 to each of the 33 trunk selector frames. 105

75 Accordingly, there will be provided a connecting device similar to the connecting device 2208 for associating the marker with the trunk selectors whenever a tone trunk is required. While the particular connecting device 2208 shown has been described for the purpose of connecting the marker to an outgoing trunk group, it will be assumed for the time being that this device serves to connect the marker with the group of tone trunks. 110 Accordingly, the relay 2001 completes a circuit for relay 2210 which may be traced from ground, through the left back contact of relay 2211, left winding of relay 2210, conductor 2125, to battery at the middle right contact of relay 2001. Relay 2210 operates and closes a holding circuit through its right winding and the winding of relay 2211, the latter relay also operating. Relays 2210 and 2211 jointly complete a circuit for the multi-contact relay 2209, which connects various leads from the test relays in Fig. 20 to the sleeve conductors of the tone trunks 318. 115

80 Inasmuch as there is only one tone trunk at each trunk selector frame, it will be neces-

sary to cancel the effect of test relays 2028 and 2030. As was previously explained, this may be accomplished by means of a cancellation relay 1923. Relay 2001 closes a circuit 5 for operating relay 1923 which may be traced through the outer right front contact of relay 2001, and thence to ground over conductor 2035 as previously traced.

To illustrate the operation of the cancellation relays, it will be assumed that the tone 10 trunk 318 appears on the trunk selector frame to which the group of test relays 2021 relates. It will further be assumed that the first tone trunk in the group, namely the one 15 appearing on the trunk selector frame to which relates the group of test relays 2020, is busy. Since the first tone trunk (not shown) is busy, the test relay 2022 relating thereto is energized in a circuit as previously 20 traced over conductor 2039, thence through contacts of the connecting device 2208, and thence over conductor 2232 to the grounded sleeve conductor of the busy tone trunk.

Inasmuch as there is no idle tone trunk on 25 the first trunk selector frame, the three trunks incoming thereto from the district selector frame 205 should be rendered non-selectable. This is effected by operating the corresponding test relays 2010, 2012 and 30 2015. Relay 2010 is operated in a circuit from battery, through its left winding, outer left contact of relay 2022, conductor 2044, inner contact of the cancellation relay 1923, thence to ground at the outer right contact 35 of relay 2022. Relay 2012 is energized in a circuit from battery, through its left winding, middle left contact of relay 2022, and thence to ground as above traced. The third relay 2015 is operated in a circuit from battery, through its left winding, inner left contact of relay 2022, and thence to ground 40 as above traced.

The test is now resumed on the second group, or namely on the second trunk selector on which appears the idle tone trunk 318. Since the trunk 318 is idle, the corresponding 45 test relay 2025 will remain deenergized. The test circuits including relay 2025 may be traced from battery, through the winding of said relay, left back contact of relay 2026, conductor 2045, through the connector 2208, conductor 2233, thence to the sleeve of the idle tone trunk 318. If, at the same time, 50 one of the three trunks incoming from the district frame 205 to its particular trunk selector frame is idle, for instance the trunk to which the test relay 2011 relates, said relay will remain deenergized when a test is performed through its right-hand winding.

The test relays having thus determined an idle path leading to a tone trunk, the relay 55 2046 is energized in a circuit from battery, through the winding thereof, left back contact of test relay 2011, left front contact of the operated test relay 2010, left front con-

tact of the preference relay 2024, conductor 2042, to ground at the outer contact of relay 2003. It will be noted that the relay 2003 is operated at this time to supply holding ground to the conductor 2042 and for the 70 test relays, in a circuit which was traceable from battery, through the winding of said relay, inner left front contact of relay 2001, conductor 2047, contacts of relays 2210 and 2211, to ground. Relay 2046 causes the operation of relay 2031 in a circuit from battery, through the winding of the latter relay, outer right back contact of relay 2030, conductor 2048, to ground at the contact of relay 2046. 80

In the manner hereinbefore explained, the connector 2105 is operated and circuits are prepared for the up-drive power magnet to the district switch 205 and the trunk connecting switch 320. These switches are set 85 as hereinbefore explained and thereby the tone apparatus 321 is associated with the calling subscriber's line and produces a tone in his receiver informing him that the called line is busy.

At the time the relay 2001 operates, it opens the previously closed circuit for relay 1604. This latter relay becomes deenergized. When the trunk selector switch 320 has been operated and the relay 1903 is energized, all 90 as previously explained, the relay 1614 operates. With relay 1614 operated and relay 1604 deenergized, the marker release relay 1613 is actuated in a circuit from battery, through its winding, middle left contact of 100 relay 1614, to ground at the back contact of relay 1604. Relay 1613 causes the release of the marker and the release of the sender as hereinbefore explained.

When the calling subscriber recognizes the 105 busy tone, he replaces his receiver on the switchhook, causing the deenergization of the supervisory relay 215, whereupon the switches involved in the established connection are restored to their normal positions. 110

Preference among final selectors.

The final selector switches 400 in each of the different choices or final groups may 115 conveniently be divided into two sub-groups for the purpose of giving each sub-group a first choice to half of the lines and second choice to the remaining half of the called subscribers' lines. This may be accomplished by splitting the multiple bank in such a manner that half of the 400 lines appear in the lower half of the banks before half of the final switches, and in the upper half of the banks before the remaining final switches. Correspondingly, the other half of the 400 120 lines will appear in the lower half of the banks before the second-mentioned half of the final switches, and in the upper half of the banks before the first-mentioned half of the final switches. In this way, a switch 125

having first preference to a given line, if taken for use need operate only over half the distance of the bank, whereas if the switch taken for use has a second choice of the calling line, it must operate under the first half and into the second half of the bank before it can reach such line. An arrangement somewhat similar to the one here described is shown in the patent to S. B. Williams, No. 1,380,857, issued June 7, 1921.

Accordingly, a numerical group of trunks leading into a given final group of switches will be divided into two sub-groups, half of the trunks leading to switches which have access as first choice to a given half of the lines, and the remaining half leading to other switches which have access as first choice to the other half of the lines. Since this is true, the marker may determine after it is received the numerical designation, which sub-group of trunks, such as the trunk 306, 307, etc., should be used. Therefore, this sub-group will be tested first, and if an idle one is found such trunk will be used. On the other hand, if the test of the trunk group reveals that all trunks are busy, then the testing relays 2000 are released and a new test is made of the trunks of the second choice group.

The two cancellation relays 1909 and 1921 are provided for the purpose of determining which sub-group of the total group of trunks leading to the final switches shall be tested. Assuming, for example, a group of 66 trunks, the first sub-group will comprise 33 of these trunks, and the second sub-group the remaining 33 trunks. Inasmuch as there are two trunks from each trunk selector frame, a convenient manner of division is to take the first trunk on each of the 33 frames for the first sub-group and the second trunk on each of the 33 frames for the second sub-group. If, therefore, it is desired to first test the trunks in the first sub-group, the relay 1921 may be operated to cancel the effect of the second trunk at each of the 33 frames. In other words, the relay 1921 substitutes in effect for relays 2028, 2030, etc. Similarly, the other cancellation relay 1909 substitutes in effect for the relays 2022, 2025, etc.

A suitable way of determining which of the relays 1909 or 1921 is to be operated, is by making use of the even or odd character of the units digit of the subscriber's line. For instance, if the units digit of the called line is even, the relay 1921 is operated in a circuit from battery, through the winding of said relay, thence through the contact of an even units relay 1813, 1815, etc., conductor 1832, outer left contact of relay 1801, conductor 1833, right back contact of relay 1606, to the grounded conductor 1624. On the other hand, if the units digit is odd, the

relay 1909 is operated in a circuit leading 65 through the contact of one of the odd units relay 1814, 1816, etc.

To conform with the operation of the cancellation relays 1909 and 1921, dependent upon the even or odd character of the units 70 digit, the subscribers' lines may be located in the final switch terminal bank according to the even or odd character of the units digit. The 200 lines with even units digits may appear in the lower half of the bank 75 before half of the final switches, and in the upper half of the bank before the remaining switches. Similarly the 200 lines with odd digits may appear in the upper half of the bank before the first-mentioned half of 80 the switches, and in the lower half of the bank before the second-mentioned half of the switches.

Thus, if the called line has an even units digit, the sub-group of trunks leading to 85 the switches having first choice at these lines will first be tested and accordingly the relay 1921 may be operated to cancel the effect in the testing relay set 2000 of all trunks of the second sub-group which lead to final 90 switches having second choice access to the called line. Correspondingly, the relay 1909 may be operated when a line having an odd units digit is called. If the relay 1921 is operated, and the trunk to which relay 2022 95 corresponds at the related frame is busy, then the other trunk at such frame which belongs to the other sub-group is cancelled by operating the three test relays 2010, 2012 and 2015, notwithstanding the fact 100 that said second trunk may be idle. Relay 2010 is operated in a circuit from battery, through its left winding, outer left contact of relay 2022, conductor 2044, inner contact of relay 1921, to ground at the outer right 105 contact of relay 2022. Relay 2012 is operated in a circuit from battery, through its left winding, middle left contact of relay 2022, thence over conductor 2044, to ground. In a similar manner, the relay 2015 is operated. 110

If, on the other hand, the units digit is odd and the relay 1909 is operated, then the trunk corresponding to relay 2022 at the first frame and the trunk corresponding to 115 relay 2025 at the second frame, etc., are cancelled. This cancellation takes place by operating the relays 2010, 2012 and 2015 for the first frame, relays 2011, 2013 and 2016 for the second frame, etc., provided the 120 first choice trunks at said frames are busy. Assuming the first choice trunk at the first frame is busy, then the test relay 2010 is operated in a circuit from battery, through its left winding, next-to-the-inner left contact of relay 2028, outer contact of relay 1909, to ground at the outermost contact of relay 2028. In a similar 125

manner, relays 2012 and 2015 are operated in circuits through the contacts of relays 2028 and 1909.

If it is found by the test relays 2000 that all of the first choice trunks are busy, then the cancellation relay 1909 or 1921, as the case may be, is released and a test is thereupon made of the group of 33 second choice trunks. If a test is first being made of a sub-group of trunks with the relay 1921 operated and all of these trunks are found busy, then a circuit is completed from ground on the conductor 1627, left contact of relay 2002, conductor 2042, outer left contact of relay 2024, left front contacts of relays 2010, 2011, 2012, etc., (these relays all being energized), thence over conductor 2049, inner left front contact of relay 2024, conductor 2050, left front contact of relay 1603, winding of relay 1605, to battery. The relay 1603 has already been operated in a circuit from battery, through its winding, left contact of relay 1606, middle right contact of relay 1608, to the grounded conductor 1622. Relay 1605 operates and causes the operation of relay 1606. Relay 1606 operates and locks to the conductor 1624. Relay 1606 at its right back contact opens the circuit of relay 1921. Relay 1921 removes the cancellation effect and permits the trunks of the second sub-group to be tested in the manner hereinbefore described in detail. If one of these second choice trunks is found idle, the connection is established thereto and the switches are operated in the manner already fully described.

Description of an interoffice connection.

It will now be assumed that the calling subscriber desires to obtain connection with a subscriber's line located in a distant office. To this end, the connection is extended through the district selector and through the trunk selector switch to an idle trunk of the group outgoing to the desired distant office. Two of these trunks, 322 and 323, are shown schematically and the manner in which their sleeve conductors are connected for testing purposes is also illustrated. It is understood that these trunks appear in trunk selector switches similar to the switch 300, and the associated apparatus is substantially the same as that shown in detail.

Assume that the trunk group relay 1601 in the marker is the relay individual to the desired group of outgoing office trunks. Accordingly, the record established in the sender by the calling subscriber when transferred to the marker registers 1500, 1501 and 1502, causes a setting of the translator 1503 in such a manner as to complete an operating circuit for the relay 1601. As was hereinbefore related, this record is transferred immediately that it is received in the sender and before the numerical record is sent to

the sender by the calling subscriber. At this time, the relay 1609 fails to operate as it did in the case of a local call, and accordingly the class relay 806 in the sender is not operated to indicate that the sender shall be reassigned with the marker following the receipt of the numerical impulses. In other words, the marker is not disassociated from the sender at this time since it is an office call.

Either the translator 1503 or the group relay 1601 may complete circuits leading back to the sender for operating the proper ones of the class relays shown in Figs. 7, 8 and 9 in order to determine the operation of the sender for this particular class of a call. The mechanism shown in Fig. 7 of the sender is for the purpose of transmitting code impulses to a distant office to set sending or relay call indicator mechanisms thereat.

For a general understanding of the manner in which class information is reverted from the marker to the sender, and of the manner in which code impulses are transmitted from the sender to a distant office, reference is made to U. S. Patent No. 1,517,331, issued December 2, 1924 to S. B. Williams. In the present disclosure, the sender is shown as utilizing a power-driven sequence switch 710 for creating and transmitting the code impulses. The specific manner in which this is done is shown in the patent to Lundell and Clark, No. 1,312,791, issued August 12, 1919.

Immediately that the relay 1601 operates, it causes the operation of an office trunk connector 2208 which is individual to the outgoing group of trunks containing the trunks 322 and 323. It will be assumed that the particular connector 2208 shown is individual to this particular group. Accordingly, the relay 2210 is operated in a circuit from ground, through the contact of relay 2211, left winding of relay 2210, conductor 2233, through the frame 1618, to battery at the contact of relay 1601.

Relay 2210 causes the operation of relay 1928 in a circuit traceable over conductor 1929, inner left back contact of relay 2001, conductor 2047, through contacts of the relays 2210 and 2211, to ground. The relay 1928 prepares for the operation of the district frame connector 2100 while the relay 2109 is operated to associate the marker testing relays 2000 with trunks outgoing to the called office. In the manner hereinbefore described, these outgoing trunks are tested by the test relays 2000, and when an idle one is located the marker is prepared to operate the district and trunk selector switches to extend the calling line through to the selected idle outgoing trunk. The test circuit for the trunk 322, for instance, may be traced from the sleeve conductor 325 thereof, back con-

tact of relay 326, thence over conductor 2233, through the connector 2208, conductor 2045, left back contact of relay 2026, to the winding of the test relay 2025.

5. After the switches have been operated, relay 1614 is energized as above explained, and the release relay 1613 operates in a circuit closed at the contact of relay 1604. In the manner heretofore described, relay 1613 10 brings about a release of the marker and its associated equipment.

After the sender has completed the transmission of code impulses representing the numerical designation over the selected interoffice trunk to the distant office, it undergoes release and the connection is prepared for conversation.

What is claimed is:

1. In a telephone system, telephone lines, 20 a plurality of first switch frames, a plurality of second switch frames, connecting trunks leading separately from each of said first frames to each of said second frames, a numerical group of trunks outgoing from 25 said second switch frames, means for selecting any one of said second frames for the purpose of extending a line therethrough to one of said numerical trunks, and means dependent upon the second frame selected for 30 extending a telephone line through any one of said first frames over a connecting trunk to the selected second frame.

2. In a telephone system, telephone lines, 35 a first switching stage having a plurality of switch frames thereat, a second switching stage having a plurality of switch frames thereat, connecting trunks leading separately from each frame at the first stage to each frame at the second stage, a numerical 40 group of trunks outgoing from said second stage and distributed among the frames thereat, means for determining one of the frames at said second stage for the purpose of extending a connection therethrough to 45 one of said numerical trunks, and means dependent upon the frame thus determined for extending a telephone line through one of the frames at the first stage to the particular frame determined at the second stage.

- 50 3. In a telephone system, subscribers' lines, a plurality of first switch frames, a plurality of second switch frames, connecting trunks leading separately from each of said first frames to each of said second frames, a numerical group of trunks outgoing from said second switch frames, a marker mechanism for selecting any one of said second frames for the purpose of extending a subscriber's line therethrough to one of said 55 numerical trunks, and means dependent upon the frame selected for extending a subscriber's line through one of said first frames over a connecting trunk to the selected second frame.

- 60 4. In a telephone system, subscribers'

lines, a plurality of first switch frames, a plurality of second switch frames, connecting trunks leading separately from each of the first frames to each of the second frames, a numerical group of trunks outgoing from 70 said second frames, means for selecting an idle numerical trunk and an idle connecting trunk leading to the same second frame in which such idle numerical trunk appears irrespective of the particular second frame 75 involved, and means dependent upon the second switch frame in which such selected idle trunks appear for extending a subscriber's line through one of said first frames over 80 said idle connecting trunk and through the corresponding second frame to said idle numerical trunk.

5. In a telephone system, telephone lines, a plurality of first switch frames, a plurality of second switch frames, connecting 85 trunks leading separately from each of said first frames to each of said second frames, a numerical group of trunks distributed among and outgoing from said second switch frames, means for selecting an idle one of 90 said numerical trunks irrespective of the second switch frame in which it appears, means for extending a telephone line through any one of said first switch frames over a connecting trunk to the second switch frame 95 in which appears said idle trunk, and means for extending the telephone line through said switch frame to the idle numerical trunk.

6. In a telephone system, subscribers' lines, 100 a plurality of first switch frames and a plurality of second switch frames, groups of connecting trunks, each group leading separately from each of said first frames to each of said second frames, a group of numerical trunks outgoing from said second switch 105 frames, means for selecting an idle connecting trunk leading to one of said second frames in which appears an idle outgoing numerical trunk irrespective of the second frame so involved, and means rendered effective as soon as the second switch frame to be 110 used is ascertained for extending a subscriber's line through any one of said first switch frames over the idle connecting trunk and through the second switch frame to 115 said idle numerical trunk.

7. The combination in a telephone system 120 of a telephone line, a plurality of first selective switch frames, a plurality of second selective switch frames, connecting trunks leading separately from each of said first frames to each of said second frames, numerical groups of trunks outgoing from said second switch frames, designation controlled means for selecting a trunk in any numerical group irrespective of the frame in which it appears, and means dependent upon the result of such selection for extending the telephone line through any one of the first frames over a connecting trunk to the par- 125 130

ticular second frame in which appears the selected numerical trunk.

8. The combination in a telephone system of a telephone line, a plurality of first selective switch frames, a plurality of second selective switch frames, trunks leading separately from each of said first frames to each of said second frames, a numerical group of trunks outgoing from said second switch frames, a plurality of said numerical trunks appearing in each of said second frames, means controlled in accordance with the designations for selecting an idle one of said numerical trunks irrespective of the frame in which it appears, and means dependent upon such selection for extending the telephone line through one of the first frames over one of said first-mentioned trunks to the particular second frame in which appears the selected numerical trunk.

9. In a telephone system, a line, a switching stage comprising a number of selective switch frames, a second switching stage also comprising a number of switch frames, a plurality of numerical divisions of apparatus, trunks leading separately from each switch frame at the first stage to each switch frame at said second stage, each of said trunks serving to extend connections into any one of said numerical divisions, means for selecting a switch at the second stage having access to the desired division and for selecting a trunk leading from the first stage to such switch, and means for operating a switch at the first stage to make connection with the selected trunk and for operating said selected switch at the second stage to make connection with such selected trunk.

10. The combination in a telephone system of telephone lines, a first and a second switching stage and a plurality of separate switching structures at each stage, connecting trunks leading separately from each structure at the first stage to each structure at the second stage, a plurality of numerical groups of trunks distributed among and outgoing from the structures at said second stage, means separate from the switches for selecting an idle trunk in any numerical group irrespective of the switching structure at said second stage in which it appears, and means dependent upon the structure in which such idle selected trunk appears for extending a telephone line through one of the structures at said first stage to said structure at the second stage.

11. The combination in a telephone system of telephone lines, a plurality of first separate switching structures, a plurality of second separate switching structures, each of said structures comprising a terminal bank and a number of movable switches, connecting trunks each leading separately from each of said first structures to each of said second

structures, a numerical group of trunks outgoing from said second switching structures, means for selecting an idle numerical trunk irrespective of the switching structure in which it appears, means for thereupon operating a switch at one of said first structures to extend a telephone line therethrough and over a connecting trunk to the particular second structure in which appears the selected idle numerical trunk, and means for operating a switch at such second structure for further extending the connection to the idle numerical trunk.

12. In a telephone system, a calling line, a numerical switching stage comprising a plurality of separate switch frames, each frame comprising a terminal bank and a plurality of cooperating switches, a numerical group of trunks outgoing from said stage and distributed among said frames, means for selecting any one of said frames for the purpose of extending the calling line therethrough, means dependent upon the particular frame selected for extending the calling line to such frame, and means for operating one of said switches to extend the calling line to one of said trunks.

13. In a telephone system, a calling line, a numerical switching stage comprising a plurality of separate switch frames each comprising a terminal bank and sets of cooperating movable terminals, a variably operative automatic switch for extending the calling line to any one of said frames, a numerical group of trunks outgoing from said stage and distributed among said frames, means for selecting any one of said frames for the purpose of extending the calling line therethrough to one of said trunks, means for controlling the operation of said automatic switch in accordance with the frame selected to extend the calling line to such frame, and means for controlling a set of movable terminals on the selected frame to extend the calling line to one of said trunks.

14. In a telephone system, a subscriber's line, a switching stage comprising a number of separate switch frames each including a terminal bank and sets of movable brushes, a variably operable automatic switch for extending the subscriber's line to any one of said frames, groups of connecting trunks each leading from said automatic switch to a different one of said frames, a group of numerical trunks outgoing from said stage and distributed among said frames, means for determining any one of said frames for the purpose of extending the subscriber's line therethrough to one of the numerical trunks, means dependent upon the frame determined for use and upon the condition of the connecting trunks leading to said frame for operating said automatic switch to extend the subscriber's line over an idle one of said connecting trunks to such determined

frame, and means for operating a set of brushes on the determined frame to make connection to the desired numerical trunk.

15. In a telephone system, a calling line, a numerical switching stage comprising a plurality of separate switch frames, each frame including a bank of terminals and movable brush sets, a plurality of numerical groups of trunks outgoing from said stage and distributed among said frames, each group having a plurality of trunks appearing separately in each frame, means for selecting an idle trunk in the proper group irrespective of the frame in which said trunk appears, means depending upon the particular frame in which the selected trunk appears for extending the calling line to such frame, and means for operating a set of brushes at the particular frame to make connection with the selected idle trunk.

16. The combination in a telephone system of subscribers' lines, a plurality of first switch frames, a plurality of second switch frames, a plurality of connecting trunks leading separately from each of said first frames to each of said second frames, a numerical group of trunks outgoing from said second frames, means for selecting any one of said second frames for the purpose of extending a line therethrough to one of said numerical trunks, means depending upon the second frame selected for extending a subscriber's line to any one of said first frames over a connecting trunk to the selected second frame, and means for utilizing the remainder of said connecting trunks, if idle, for subsequent and simultaneous connections.

17. In a telephone system, a line, a switching stage comprising a number of switch frames, trunks incoming to said frames, a group of trunks outgoing from said stage and distributed among said frames, a testing device for testing all incoming and outgoing trunks for determining the frame in which appears an idle incoming trunk and an idle outgoing trunk, and means dependent upon the result of the test for extending said line over the idle incoming trunk through the frame to the idle outgoing trunk.

18. In a telephone system, a line, a switching stage comprising a number of separate selecting switching structures, a separate group of incoming trunks leading to each structure, a numerical group of trunks outgoing from said stage, each structure having a plurality of said outgoing trunks appearing therein, means for making a test of all trunks incoming to and outgoing from each structure to select any one of such structures which has an idle trunk incoming thereto and an idle trunk outgoing therefrom, and means depending upon the outcome of the test for selectively extending

said line over the idle path comprising said incoming and outgoing trunks.

19. In a telephone system, a line, a stage comprising a number of separate switching structures, a separate group of incoming trunks leading to each structure, a numerical group of outgoing trunks leading from said stage, each structure having a plurality of said outgoing trunks appearing therein, means for making a test of all trunks incoming to and outgoing from each structure to select any one of said structures which has an idle trunk incoming thereto and an idle trunk outgoing therefrom, means for rendering artificially busy all trunks incoming to a particular structure if all trunks outgoing therefrom are actually busy, and means depending upon the result of the test for selectively extending said line over the idle path comprising an incoming and an outgoing trunk.

20. In a telephone system, a line, a switching stage comprising a number of separate switch frames, a separate group of incoming trunks leading to each frame, a plurality of variable-sized groups of numerical trunks outgoing from said stage, each frame having a plurality of trunks of each group appearing therein, a set of test relays common to all groups of trunks for making a test of all trunks incoming to and all trunks of a group outgoing from each frame to select any one of said frames which has an idle trunk incoming thereto and an idle trunk of the proper group outgoing therefrom, and means depending upon the test for selectively extending said line over the idle path comprising the idle incoming trunk and the idle outgoing trunk.

21. In a telephone system, a line, a switching stage comprising a number of switch frames, trunks incoming to said frames, a group of trunks outgoing from said stage and distributed among said frames, a testing device for testing all incoming and outgoing trunks for determining the frame in which appears an idle incoming trunk and an idle outgoing trunk, means dependent upon the result of the test for extending said line over the idle incoming trunk through the frame to the idle outgoing trunk, and means for extending simultaneous connections over the other trunks incoming to and outgoing from said determined frame.

22. In a telephone system, telephone lines, a plurality of progressively operable selective switches arranged in series, and a common registering means separate from said switches for simultaneously controlling the operation of all switches to establish a connection between two of said lines.

23. In a telephone system, telephone lines, a plurality of successive switching stages

each having a plurality of progressively operable selective switches thereat, means for determining a switch at each of said stages to be used in the establishment of a connection, and means common to all switches for controlling the simultaneous operation of the determined switches to establish a connection between two of said lines.

24. In a telephone system, telephone lines, a plurality of separate switching stages each having a plurality of progressively operable selective switches thereat, a switch controlling marker arranged to receive called line designations for the purpose of determining a particular switch at each of said stages to be utilized in the establishment of a connection, and means controlled by said marker for simultaneously operating the determined switches to extend a connection between a calling and a called line.

25. The combination in a telephone system of telephone lines, a plurality of switch frames each including a terminal bank and a number of movable sets of brushes, a second plurality of switch frames each including a terminal bank and a plurality of sets of movable brushes, means for selecting any one of said second switch frames for the purpose of establishing a connection between a calling and a called line, and means common to all of said frames for controlling the simultaneous movement of a set of brushes at one of said first frames and a set of brushes at the determined one of said second frames to establish the desired connection between a calling and a called line.

26. The combination in a telephone system of a telephone line, selective switches, a registering device for recording designations, a switch controlling mechanism, means effective when a part of a designation has been recorded for connecting said mechanism to said registering device and then disconnecting the same therefrom, means for subsequently causing the reconnection of said mechanism to said device, said mechanism being affected by the registering device during its connection therewith, and means controlled by said mechanism for operating said switches to extend the telephone line.

27. The combination in a telephone system of a telephone line, selective switches, a registering device for recording designations, a switch controlling mechanism, means effective when a portion of a designation has been recorded for connecting said mechanism to said registering device and then disconnecting the same therefrom, means effective when the remainder of the designation has been recorded for causing the reconnection of said mechanism to said device, said mechanism being affected by the registering device during its connection therewith, and means controlled by said

mechanism for operating said switches to extend the telephone line.

28. The combination in a telephone system of a telephone line, selective switches, a sender responsive to impulses transmitted over the telephone line to record designations, a switch controlling mechanism, means effective when a portion of the designation impulses have been received and recorded for connecting said mechanism to said sender and then disconnecting the same therefrom, means for subsequently causing the reconnection of said mechanism to said sender after the remaining impulses have been received, said mechanism being affected by the sender during its connection therewith, and means controlled by said mechanism for operating said switches to extend the telephone line.

29. The combination in a telephone system of a telephone line, selective switches, a sender for recording designations, a plurality of switch controlling markers, means effective when a portion of a designation has been recorded for connecting the sender to one of said markers and for disconnecting the same therefrom, means for subsequently causing the reconnection of said sender either to the same or to another of said markers after the remainder of the designation has been recorded in said sender, said markers being affected during connection with said sender, and means controlled by said markers for selectively operating said switches.

30. The combination in a telephone system of a telephone line, selective switches, a recording sender for recording designations, a plurality of switch controlling markers, means effective when a part of a designation has been recorded for connecting the sender to any one of said markers and then disconnecting the same therefrom, said marker serving while connected to establish a class record in the sender, means for causing the connection of said sender to any one of said markers when the remainder of the designation has been recorded for the purpose of transferring the recorded designation from the sender to the marker, and means controlled by said last-mentioned marker for selectively operating said switches in accordance with said designations.

31. The combination in a telephone system of selective switches for establishing different classes of connections, a register sender for recording designations, a plurality of switch controlling markers, means effective during the registration of a designation for connecting said sender to one of said markers and for transferring thereto the portion of the designation which has already been recorded in the sender, means dependent upon the class of the call being extended for transferring from the marker to the sender

- a record of such class and for thereupon causing the release of said marker, means after the remaining portion of the designation has been recorded in the sender for causing the connection of said sender to any one of said markers and for transferring thereto the remaining portion of the designation record, and means controlled by said latter marker for selectively operating said switches.
- 10 32. In a telephone system, a group of called subscribers' lines, a plurality of trunks divided into two groups, all trunks having access to all of said lines and each group having first choice access to a different half 15 of said lines, a testing mechanism for first testing the group of trunks having first choice access to a given called line, and means effective if all of said first choice trunks are busy for causing said testing mechanism to 20 test the second choice trunks.
33. In a telephone system, a group of subscribers' lines, a group of trunks arranged in two sub-groups, each sub-group having first choice access to a different half of said lines and second choice access to the remaining 25 half of said lines, a selective switch for each of said trunks for extending the same to any of said lines, a testing mechanism common to all of said trunks for making a test first of the sub-group of trunks having first 30 choice access to a particular called line, and means if all of said first choice trunks are busy for causing said testing mechanism to make a test of the second choice sub-group 35 of trunks.

In witness whereof, I hereunto subscribe my name this 11th day of November A. D. 1924.

WARREN W. CARPENTER.
